ABSTRACT

A fuel injector for injecting fuel into a cylinder of an internal combustion engine is disclosed, wherein fuel is received from a variable pressure fuel supply and is supplied to a chamber in the injector, the injector also having spray holes for discharging fuel from said chamber to the cylinder. A reciprocable plunger in the injector is utilized to decrease the volume of the chamber and thus increase the pressure of the fuel therein. A pressure actuated valve in the chamber serves to permit fuel injection through the spray holes only when the pressure in the chamber, due to movement of the plunger, reaches a predetermined value sufficient to open the valve. The injector also includes a connection between the chamber and a low pressure zone or drain during part of the cycle of movement of the plunger. This connection permits fuel to be sucked into the chamber during said part of the cycle from the drain rather than from the supply. Since the plunger does not suck fuel from the supply, the quantity of fuel entering the chamber from the supply will be a function of the pressure of the fuel delivered by the supply.

FUEL INJECTOR

In one type of fuel injection nozzle used in fuel supply systems of compression ignition engines the spray holes for injecting fuel into a cylinder are normally closed by a valve. Such an injector includes an injector body having the spray holes formed therein, and the valve which normally closes the spray holes is movable to open the spray holes in response to an increase in pressure within the injector body. A pumping member, usually a cam operated plunger within the injector body, is operable during an injection stroke to increase the fuel pressure to the point where the valve opens and permits flow of the fuel out of the spray holes.

Further, Reiners U.S. Pat. No. 3,159,152 discloses a fuel supply system wherein the quantity of fuel injected into each cylinder in each cycle of the engine is dependent upon the pressure of the fuel supplied to the injectors. This pressure may be controlled in various ways, as by the engine speed or by an operator and the pressure is variable down to a low pressure level which is necessary to provide the small fuel quantities required at idling speeds.

It has not heretofore been possible satisfactorily to use an injector of the character described above in a variable pressure fuel supply system because they cannot respond to low fuel pressure levels and because conventional injectors of this character create a suction action during the retraction stroke of the pumping member. Such a suction action would make such a conventional injector unresponsive to changes in the pressure of the fuel supplied to the injector, thus losing the advantages inherent in a variable pressure fuel system.

It is therefore a principal object of the present invention to provide a novel injector of the foregoing general character, which is usable in a variable pressure fuel system. In applicant's injector forms, any tendency of the injector to suck fuel from the variable pressure supply is eliminated by providing a connection to a low pressure zone or drain during at least part of the retraction stroke of the pumping member. Thus, any fuel sucked into the injector comes from the drain which feature enables the injector to be responsive to the pressure of the fuel from the supply. Further, the applicant's injector responds to low fuel pressure levels and it includes an advantageous method of terminating injection.

Other objects and advantages of the invention will become apparent from the following detailed description and accompanying drawings, wherein:

FIG. 1 is an enlarged longitudinal sectional view of a fuel injector embodying the features of the invention and showing the positions of the parts thereof during one portion of the operating cycle of the injector;

FIG. 2 is a fragmentary longitudinal sectional view taken substantially along the line 2—2 of FIG. 1;

FIG. 3 is a longitudinal sectional view of the lower portion of the injector shown in FIG. 1 and showing certain parts of the injector in the positions they occupy during another portion of the operating cycle of the injector;

FIG. 4 is a fragmentary longitudinal sectional view taken substantially along the line 4—4 of FIG. 3;

FIG. 5 is a longitudinal sectional view, similar to FIG. 3, but showing certain parts of the injector in the positions they occupy during still another portion of the operating cycle of the injector;

FIG. 6 is a transverse sectional view taken along the line 6—6 of FIG. 1;

FIG. 7 is an enlarged longitudinal sectional view of another fuel injector embodying the features of the invention and showing the positions of the parts thereof during one portion of the operating cycle of the injector;

FIG. 8 is a fragmentary, longitudinal sectional view taken along the line 8—8 of FIG. 7;

FIG. 9 is a longitudinal sectional view of the lower portion of the injector shown in FIG. 7 and showing certain parts of the injector in the positions they occupy during another portion of the operating cycle of the injector;

FIG. 10 is a fragmentary longitudinal sectional view taken along the line 10—10 of FIG. 9;

FIG. 11 is a longitudinal sectional view, similar to FIG. 9, but showing certain parts of the injector in the positions they occupy during still another portion of the operating cycle of the injector;

FIG. 21 is a fragmentary longitudinal sectional view, taken substantially along the line 21—21 of FIG. 20;

FIGS. 22 and 23 are fragmentary longitudinal sectional views of the lower portion of the injector shown in FIG. 20, and show certain parts thereof in the positions they occupy during different portions of the operating cycle of the injector;

FIG. 24 is a fragmentary longitudinal sectional view taken along the line 24—24 of FIG. 22;

FIG. 25 is a generally transverse sectional view taken along the line 25—25 of FIG. 20;

FIG. 26 is an enlarged longitudinal sectional view of another fuel injector embodying the features of the invention and showing the positions of the parts thereof during one portion of the operating cycle of the injector;

FIGS. 27 and 28 are fragmentary longitudinal sectional views of the lower portion of the injector shown in FIG. 26, and show certain parts thereof in the positions they occupy during different portions of the operating cycle of the injector;

FIG. 29 is a generally transverse sectional view taken substantially along the line 29—29 of FIG. 28;

FIG. 30 is an enlarged longitudinal sectional view of another fuel injector embodying the features of the invention and showing the positions of the parts thereof during one portion of the operating cycle of the injector;

FIGS. 31 and 32 are fragmentary longitudinal sectional views of the lower portion of the injector shown in FIG. 30, with portions thereof broken away, and show certain parts thereof in the positions they occupy during different portions of the operating cycle of the injector;

FIG. 33 is a generally transverse sectional view taken substantially along the line 33—33 of FIG. 30;

FIG. 34 is an enlarged, longitudinal sectional view of another fuel injector embodying the features of the invention and showing the positions of the parts thereof during one portion of the operating cycle of the injector;

FIGS. 35 and 36 are fragmentary longitudinal sectional views of the lower portion of the injector shown in FIG. 34, and show certain parts of the injector in the positions they occupy during different portions of the operating cycle of the injector;

FIG. 37 is an enlarged, longitudinal sectional view of another fuel injector embodying the features of the invention and showing the positions of the parts thereof during one portion of the operating cycle of the injector;

FIG. 38 is a fragmentary longitudinal sectional view taken substantially along the line 38—38 of FIG. 37;

FIG. 39 is a longitudinal sectional view of the central portion of the injector shown in FIG. 37, but showing one of the parts thereof in the position it occupies during a different portion of the operating cycle of the injector;

FIGS. 40 and 41 are fragmentary longitudinal sectional views of the lower portion of the injector shown in FIG. 37, and show certain parts thereof in the positions they occupy during different portions of the operating cycle of the injector;

FIG. 42 is a generally transverse sectional view taken along the line 42—42 of FIG. 37;

FIG. 43 is an enlarged, longitudinal sectional view of another fuel injector embodying the features of the injector and showing the positions of the parts thereof during one portion of the operating cycle of the injector;

FIGS. 44 and 45 are fragmentary longitudinal sectional views of the lower portion of the injector shown in FIG. 43 and show certain parts thereof in the positions they occupy during different portions of the operating cycle of the injector; and

FIG. 46 is a generally transverse sectional view taken along the line 46—46 of FIG. 45.

Briefly described, the present invention contemplates a novel fuel injector that is adapted for use in a fuel supply system for an internal combustion engine of the compression ignition type. A fuel supply system with which the present injector is adapted for use is disclosed and claimed in the Reiners U.S. Pat. No. 3,159,152 issued Dec. 1, 1964.

The fuel injector herein contemplated has an elongated body having variable volume chamber means therein having an opening adapted to communicate with the cylinder of the associated engine. A pressure

actuated valve member is movably mounted in the injector body and is urged in a direction to close the opening in the variable volume chamber means by a spring, such spring preventing the valve member from moving to a position permitting fuel to flow through the opening in the variable volume chamber means until the pressure therein rises to a predetermined value.

The injector body further includes fluid displacement means which is reciprocably mounted therein and which in part defines the variable volume chamber means. A fuel supply passage is also provided in the injector body, such passage having one end connected to the variable volume chamber means and the other end adapted to be connected to a source of fuel under variable pressure so that varying quantities of fuel are supplied to the variable volume chamber means for controlling the power output of the engine.

In all but one of the embodiments of the injector, to be hereinafter described in detail, the fluid displacement means comprises a plunger reciprocably mounted in a bore in the injector body, and a piston movable in response to movement of the plunger. In these embodiments, the piston determines the volume of the variable volume chamber means, while in the one embodiment the plunger alone determines the volume of the variable volume chamber means. In all but two of the embodiments, the piston is mounted in the bore of the plunger, while in these two embodiments the piston is mounted in a separate bore in the injector body.

In all of the embodiments which utilize pistons to determine the volume of the variable volume chamber means, the size of the variable volume chamber means at the start of the injection phase of the injection cycle is determined by the position of the piston in its bore and such position is controlled by the pressure of the fuel supplied to the injector. However, since the maximum extent of movement of the piston in its bore is limited by a stop at one end of the piston bore, the volume of the variable volume chamber means is also limited to a predetermined maximum. Such stop either comprises one end of the plunger, one end of the plunger bore, or one end of a separate bore in the injector body in which the piston is mounted. In the embodiment in which the plunger alone determines the volume of the variable volume chamber means, since the stroke of the plunger is controlled by a cam and thus does not change, the volume of the variable volume chamber means of this embodiment is likewise limited to a predetermined maximum. Consequently, in all embodiments, the maximum quantity of fuel that can be injected by the injector during any one cycle of operation is limited and cannot be increased even though the pressure of the fuel supplied to the injector is caused to exceed some predetermined maximum or the drain passage of the injector is restricted in an undesired manner.

In all of the embodiments, the variable volume chamber means of the injector is in two parts, namely, a fuel receiving chamber and a fuel injection chamber. The fuel receiving chamber is separated from the fuel injection chamber and is connected thereto by a connecting passage in the injector body.

In all of the embodiments of the invention, preventing means is provided for preventing gas or other foreign particles from flowing from the receiving chamber into the fuel supply passage toward the source. Such preventing means prevents possible contamination of

the fuel supply to other injectors if the valve member of an injector should stick in an open position.

In all of the embodiments of the invention, the injector body includes a drain passage which permits excess fuel to be freely expelled from the injector during the operating cycle thereof. In the embodiments which utilize a piston to determine the variable volume chamber means, one end of the drain passage communicates with the opposite side of the piston from the side which defines the variable volume chamber means. The other end of the drain passage is adapted to be connected to an associated drain. In the embodiment of the invention in which the plunger alone determines the variable volume chamber means, the one end of the drain passage communicates directly with the variable volume chamber means.

In all of the embodiments, pressure relief passage means is provided in the injector body for relieving the pressure in the variable volume chamber means shortly before the plunger completes its fuel injection stroke. Such pressure relief passage means has one end connected to the drain passage and the other end connected to the variable volume chamber means, the connection of the one end of the pressure relief means being cyclically established and interrupted by the plunger. In all but one of the embodiments, the pressure of the fuel in the variable volume chamber means is vented to the drain passage of the injector while in the one embodiment, such pressure is vented to the fuel supply passage.

In one of the embodiments, an arrangement is provided whereby the force exerted by the spring on the valve member tending to move the valve member to a closing position increases as the plunger moves in a direction to inject fuel. Such arrangement provides a sharp cutoff of fuel at the end of the fuel injection stroke of the plunger and reduces the possibility of secondary injection.

The Embodiment Shown in FIGS. 1-6

In FIGS. 1-6, inclusive, a fuel injector embodying the features of the present invention is illustrated. The injector shown in the figures comprises an elongated injector body 101 which, in the present instance, is of a multiple-piece construction so that replacement of the parts thereof which are subject to wear or other reason for renewal is facilitated. However, a unitary or one-piece construction could be utilized, if desired.

The injector body 101 thus includes a generally cylindrical body member 102, a nozzle member 103 and a pair of generally cylindrical, upper and lower spacer members 104 and 105, respectively, located between the body member 102 and nozzle member 103. The nozzle member 103 and spacer members 104 and 105 are arranged in end-to-end relation and are held in such relation by a tubular retainer 106. In the present instance, the upper end, indicated at 107, of the retainer 106 is internally threaded, as at 110, to receive the threaded lower end, indicated at 111, of the body member 102. The lower end of the retainer 106 is provided with an internal flange 112 for engaging an annular, radially outwardly extending flange 113 on the nozzle member 103. Thus, when the retainer 106 is threaded onto the lower end 111 of the body member 102 as shown in FIG. 1, the body member 102, nozzle member 103 and intermediate spacer members 104 and 105 are held in abutting, end-to-end relation.

The body member 102 has a central, axial bore 114 therethrough in which a plunger 116 is reciprocably mounted. The plunger 116 includes a control portion 117, and a sleeve portion 118 secured to the upper end of the control portion 117. A flange 122 is provided on the upper end of the sleeve portion 118 to provide an abutment for one end of a coil spring 123 disposed around the sleeve portion 118. The other or lower end of the coil spring 123 bears against the bottom 124 of a large counterbore 126 in the upper end of the body member 102. The spring 123 is normally under compression and tends to urge the plunger 116 upwardly.

Downward movement of the plunger 116 is effected by an elongated rod or link 127 mounted in the sleeve portion 118 of the plunger 116. The upper end of the link 127 is adapted to be engaged by a rocker arm (not shown) which is actuated by the engine in a well-known manner.

As heretofore mentioned, the injector body 101 includes variable volume chamber means for receiving a quantity of fuel from a source thereof under variable pressure through a fuel supply passage 130 having one end connected to the variable volume chamber means and the other end thereof adapted to be connected to said source. Said other end of the fuel supply passage 130, in the present instance, includes a circumferential groove 131 in the outer surface of the body member 102, the groove 131 being adapted to register with an associated fuel supply bore or rail (not shown) in the cylinder head of the engine. A transverse bore 132 extends inwardly from the groove 131 and a plug 133 (FIG. 1) having a balancing orifice 134 therethrough is threaded into the outer end of the bore 132. The balancing orifice 134 restricts and meters the flow of fuel through the fuel supply passage 130 and a filtering screen assembly 136 may be mounted in the groove 131 around the plug 133 to prevent foreign particles from entering the fuel supply passage 130.

The inner end of the transverse bore 132 is intersected by the upper end of a longitudinal bore 137 in the injector body member 102, and the lower end of the longitudinal bore 137 is counterbored as at 138 to define an annular seat 139 for a check ball 140 mounted in the counterbore 138. The check ball 140 comprises preventing means for preventing fuel from flowing out of a receiving chamber in the injector body 101, to be hereinafter described in detail, and in a reverse direction through the fuel supply passage 130 into the fuel supply rail in the engine cylinder head during the fuel injection phase of the injection cycle. The lower end of the counterbore 138 communicates with a shallow, circular cavity or recess 141 in the upper end face of the spacer member 104. The lower end of the plunger bore 114 also communicates with the cavity 141.

The aforementioned variable volume chamber means is in two parts and comprises a receiving chamber 142 and a fuel injection chamber 143. The receiving chamber 142, in the present instance, constitutes the cavity 141 in the upper end face of the spacer member 104 and the portion of the plunger bore 114 below a piston in the form of a ball 144 that is loosely fitted in the plunger bore 114 below the lower end face, indicated at 145, of the control portion 117 of the plunger 116. The fuel injection chamber 143 is provided by a cavity in the nozzle member 103, adjacent the lower end thereof.

In order to provide a connection between the receiving chamber 142 and the fuel injection chamber 143, a connecting passage, indicated generally at 146, is provided. The passage 146, in the present instance, comprises at least one and preferably a pair of diametrically spaced, longitudinal bores 147 and 148 in the spacer member 104, the upper ends of the bores 147 and 148 extend from the cavity 141 and the lower ends of the bores 147 and 148 intersect an annular groove 150 in the lower end face of the spacer member 104. Another longitudinal bore 151 is provided in the lower spacer member 105, the bore 151 being located in the spacer member 105 so that the upper end thereof registers with the annular groove 150 when the parts of the injector of FIG. 1 are in assembled relation.

The lower end of the longitudinal bore 151 may be counterbored as at 152 to define an annular seat 153, and a check ball 154 may be mounted in the counterbore 152 for engaging the seat 153. If so provided, the check ball 154 comprises preventing means for preventing gas or pressure waves from passing upwardly in the bore 151 from the fuel injection chamber 143 toward the balancing orifice 134 and into the associated fuel supply bore or rail in the cylinder head of the engine in the event of failure or malfunction of the injector.

The counterbore 152 registers with an annular groove 155 in the upper end face of the nozzle member 103, and a slanting bore 156 in the nozzle member 103 interconnects the groove 155 with the fuel injection chamber 143. Thus, the connected longitudinal bores 147 and 151 in the spacer members 104 and 105, respectively, and the bore 156 in the nozzle member 103 comprise the connecting passage 146 which connects the receiving chamber 142 with the fuel injection chamber 143.

As heretofore mentioned, the variable volume chamber means includes an opening adapted to communicate with the cylinder of the engine with which the injector of FIG. 1 is associated and through which fuel is injected into the cylinder. In the present instance, such opening comprises a plurality of minute, circumferentially spaced, generally radially extending holes 157 in the lower end of the nozzle member 103, the inner ends of the holes 157 being adapted to be placed in communication with the fuel injection chamber 143 during the fuel injection phase of the injection cycle.

For establishing communication between the fuel injection chamber 143 and the holes 157 so that fuel under pressure may flow therethrough and into the associated cylinder when the pressure of the fuel in the fuel injection chamber reaches a predetermined value, and for interrupting such communication, a valve member is provided. Such valve member is indicated generally at 158 and includes a valve body 159 shiftably mounted in an axial bore 160 in the nozzle member 103 in close-fitting relation therewith. The valve body 159 includes a reduced diameter portion 162 which extends downwardly from the lower end thereof and which defines a shoulder or fluid pressure reaction surface 163 on the valve body 159. The lower end of the reduced diameter portion 162 is tapered as at 164 for engagement with a complementally shaped seat 166 at the lower end of the fuel injection chamber 143. The inner ends of the holes 157 open into a depression below the seat 166 in the nozzle member 103. Thus, the fuel flow from the fuel injection chamber 143 to the

holes 157 is prevented when the tapered lower end 164 of the valve body 159 engages its seat 166.

The lower end 164 of the valve member 158 is normally urged toward its seat 166 by a coil spring 172 mounted in a cavity 173 in the spacer member 105 with the upper end of the spring 172 engaging the lower end face of the spacer member 104. The lower end of the spring 172 engages an abutment in the form of a circular plate 174 at the lower end of the cavity 173, the lower face of the plate 174 being seated on the upper end of an extension 177 on the upper end of the body portion 159 of the valve member 158. The spring 172 is precompressed and holds the lower end 164 of the valve member 158 on its seat 166 until a predetermined pressure is obtained in the fuel injection chamber 143 sufficient to overcome the force of the spring 172 and lift the valve member 158 off of its seat 166.

As heretofore mentioned, a piston in the form of the ball 144 is mounted in the plunger bore 114 between the lower end face 145 of the plunger and the cavity 141 in the upper end face of the spacer member 104. The ball 144 is loosely fitted in the plunger bore 114 and is movable in response to movement of the plunger. Since the ball 144 determines the volume of the receiving chamber 142 and is movable in response to movement of the plunger 116, the plunger and ball 144 comprise fluid displacement means for reducing the volume of the receiving chamber 142 and for increasing the pressure therein and in the fuel injection chamber 143.

In addition, since the volume of the receiving chamber 142 is determined by the ball 144 and since the volume of the receiving chamber 142 will be at a maximum when the ball 144 is engaged with the end face 145 of the plunger when the latter is at the end of its upward stroke, the end face 145 of the plunger comprises a stop limiting movement of the ball 144 in one direction and the volume of the receiving chamber 142 to a predetermined maximum. Consequently, the maximum quantity of fuel that can be injected into the associated cylinder is also limited.

In order to provide for variation of the volume of the receiving chamber 142, the space, indicated at 183, between the upper side of the ball 144 and the lower end face 145 of the plunger 116 is connected to a drain or other low pressure zone, such as a drain rail in the engine cylinder head. Connection of the space 183 to a drain permits fuel to be freely drawn into the space 183 from the drain and thus prevents any substantial vacuum from being created in the space 183, which would tend to cause the ball 144 to remain in contact with or closely follow the lower end face 145 of the plunger 116 during its upward stroke. Thus, the extent of upward movement of the ball 144 in the plunger bore 114 is determined substantially only by the pressure of the fuel in the fuel supply passage 130 and this pressure is a direct function of the pressure of the fuel in the associated fuel supply rail in the engine cylinder head.

Connection of the space 183 above the ball 144 to the drain is provided by a drain passage having one end connected to the space 183 and its other end adapted to be connected to the drain. Such drain passage, in the present instance, comprises an axial bore or duct 184 in the lower end of the control portion 117 of the plunger 116, the lower end, indicated at 186, of the duct 184 opening in the end face 145 of the plunger

and being located so as to be closed by the ball 144 when the latter engages the end face 145.

The upper end of the duct 184 intersects a cross bore 187 in a reduced diameter portion 188 of the control portion 117 of the plunger, the reduced diameter portion 188 defining an annular space 189 in the plunger bore 114. The annular space 189 is in continuous registry with the inner end, indicated at 192, of a bore 193 slanting upwardly and outwardly in the injector body member 102 from the plunger bore 114. The outer or upper end of the bore 193 opens into a circumferential groove 194 in the outer surface of the injector body member 102, the groove 194 being adapted to communicate with an associated drain bore or return rail in the cylinder head of the engine when the injector body 101 is seated in the cylinder head. Thus, the space 183 above the ball 144 is connected to the drain so long as the lower end 186 of the duct 184 is not closed by the ball 144.

Injection of fuel into the engine cylinder occurs in a manner to be described hereafter in connection with the description of the operation of the injector.

The injector of FIG. 1 further includes pressure relief passage means for relieving the pressure in the receiving chamber 142 and fuel injection chamber 143 as the plunger 116 is approaching the end of its downward or fuel injection stroke. Such pressure relief passage means, in the present instance, comprises a pair of diametrically spaced, longitudinal bores 197 and 198 (FIGS. 2, 4 and 6) in the injector body member 102. The lower ends of the bores 197 and 198 communicate with the cavity 141 in the upper end face of the spacer member 104, and the upper ends of the bores 197 and 198 respectively intersect a pair of diametrically arranged transverse bores 201 and 202 in the body member 102. The outer ends of the transverse bores 201 and 202 are closed, as by plugs, and the inner ends thereof, indicated at 203 and 204, respectively, are restricted and open into the plunger bore 114. The restricted inner ends 203 and 204 of the bores 201 and 202 are located so as to communicate with the annular space 189 before the plunger 116 reaches the end of its downward or fuel injection stroke. Thus, when the lower or control edge, indicated at 206, of the reduced diameter portion 188 moves across the ends 203 and 204 of the transverse bores 201 and 202, pressure in the receiving and fuel injection chambers 142 and 143 is relieved and the fuel injection phase of the injection cycle is terminated. However, since the inner ends 203 and 204 are restricted, the flow therethrough is small and the valve member 158 moves downwardly toward its seat at a slower rate than if the ends 203 and 204 were unrestricted. Such downward movement of the valve member 158 causes fuel to be displaced from the fuel injection chamber 143 upwardly to the receiving chamber 142 and ultimately to the transverse bores 201 and 202. The restricted inner ends 203 and 204 prevent such fuel from rapidly flowing to the drain and hence prevent abrupt closing of the valve member 158.

In order to prevent restriction of movement of the valve member 158 due to the presence of fuel in the valve spring cavity 173, the cavity 173 is vented to drain. Such venting is provided by a radial bore 207 in the spacer member 105, which extends from the cavity 173 to an annular groove 208 in the outer periphery of the spacer member 105. The groove 208 opens into an annular clearance 209 between the spacer members

105 and 304 and the retainer 106. The upper end of the clearance 209 communicates with the lower end of a longitudinal bore 212 in the injector body member 302 and the upper end of the bore 212 intersects the drain bore 193 to complete the vent connection to drain.

OPERATION OF THE EMBODIMENT SHOWN IN FIGS. 1-6

At the completion of an injection cycle of the injector shown in FIGS. 1-6, inclusive, and prior to the beginning of another cycle, the parts of the injector are in the positions shown in FIGS. 1 and 2. Thus, fuel under pressure maintains the ball piston 144 in the plunger bore 114 engaged with the lower end face 145 of the plunger 116 so that the ball closes the lower end 186 of the duct 184 in the control portion 117 of the plunger 116. The ball 144 is held against the lower end face 145 of the plunger by the differential pressure between the pressure in the receiving chamber 142 and the pressure in the space 183 above the ball, the space 183 being connected to the drain.

As the injection cycle begins, the plunger 116 begins to move upwardly in its bore. If the pressure of the fuel in the associated fuel supply bore or rail is insufficient to fill the receiving chamber 142 at a rate such as will maintain the ball 144 engaged with the lower end 186 of the duct 184 as the plunger 116 moves upwardly, the ball 144 will separate from the lower end 186 of the duct and the space 183 above the ball will increase. Such condition is shown in FIGS. 3 and 4.

During the upward stroke of the plunger 116, the lower or control edge 206 of the reduced diameter portion 188 moves across and closes the inner, restricted ends 203 and 204 (FIGS. 2 and 4) of the transverse pressure relief bores 201 and 202. Consequently, communication between the fuel receiving chamber 142 and the drain bore 193, and hence between the fuel injection chamber 143 and the drain bore, is cut off.

When the plunger 116 reaches the end of its upward stroke, the volume of the receiving chamber 142 will be at a maximum if the pressure of the fuel in the supply rail is great enough to cause the ball 144 to engage the end face 145 of the plunger 116 and close the lower end 186 of the plunger duct 184. However, if the pressure in the supply rail has been less, the ball 144 will be spaced below the lower end face 145 of the plunger, as shown in FIG. 3, and the volume of the receiving chamber 142 will be less than maximum. The latter condition usually occurs when an engine utilizing injectors of the character shown in FIG. 1 is operating at less than its maximum power output.

Assuming that the pressure in the fuel supply bore or rail has been insufficient to maintain the ball 144 engaged with the lower end 186 of the duct 184 in the control portion 117 of the plunger, as the plunger 116 begins its downward stroke fuel in the space 183 will be forced upwardly through the duct 184, outwardly through the cross bore 187 to the annular space 189, and thence through the bore 193 and circumferential groove 194 in the injector body member 102 to the drain rail in the cylinder head of the engine. The volume of the space 183 will decrease until the lower end face 145 of the plunger 116 contacts the ball 144 and the latter closes the lower end 186 of the duct 184. The latter condition is illustrated in FIG. 5.

When the lower end face 145 of the plunger 116 contacts the ball 144 on its downward stroke and the

ball 144 closes the lower end 186 of the duct 184, continued downward movement of the plunger 116 will cause fuel to be displaced from the receiving chamber 142. Such displacement initially causes the check ball 140 to move upwardly against its seat 139 so that fuel will be prevented from flowing in a reverse direction through the fuel supply passage 130 and into the fuel supply rail. As soon as the check ball 140 seats, the pressure of the fuel in the receiving chamber 142, connecting bores 147, 151 and 156 of the connecting passage 146, and fuel injection chamber 143, will rapidly rise. When the pressure acting on the reaction surface 163 of the valve member 158 reaches a predetermined value sufficient to overcome the force of the coil spring 172, the valve member 158 will move upwardly in its bore 160. Consequently, fuel under high pressure in the fuel injection chamber 143 will be injected through the nozzle holes 157 and into the associated cylinder. The clearance shown in FIG. 5 between the lower end 164 of the valve member 158 and its seat 166 is exaggerated for clarity of illustration.

Injection continues until the control edge 206 of the reduced diameter portion 188 moves past the restricted inner ends 203 and 204 (FIGS. 2, 4 and 6) of the pressure relief bores 201 and 202. When this occurs, the pressure in the receiving chamber 142, fuel injection chamber 143, and connecting passage 146 begins to drop due to the connection established between the annular space 189 and the drain rail in the engine cylinder head through the pressure relief bores 201 and 202. However, since the inner ends 203 and 204 of the pressure relief bores 201 and 202 are restricted, the flow therethrough is small and the lower end 164 of the valve member 158 is prevented from impacting against its seat 166 at the completion of each injection cycle. In addition, the gradually decreasing pressure in the receiving chamber 142 acts on the ball 144 and hence on the plunger 116 to prevent overtravel of the plunger on its downward or fuel injection stroke. Hence, the possibility of damage to the ball 144 is reduced.

When the pressure in the receiving and fuel injection chambers 142 and 143 reduces to a value such as will permit the spring 172 to cause the lower end 164 of the valve member 157 to engage its seat 166, injection of fuel into the associated cylinder ceases. When the plunger 116 reaches the end of its downward or fuel injection stroke, as illustrated in FIG. 1, the injection cycle is completed.

It should be noted that the pressure relief bores 201 and 202, and their restricted inner ends 203 and 204, are arranged diametrically with respect to the plunger bore 114. Such arrangement prevents the imposition of a side load on the control portion 117 of the plunger 116 during the fuel injection phase of the injection cycle, which might cause excessive wear.

In addition, the annular grooves 150 and 155 in the lower end face of the spacer member 104 and upper end face of the nozzle member 103, respectively, prevent any unbalance of pressure forces on the engaging end faces of the members 104, 105 and 103. Consequently, any tendency of these members to cock with respect to the longitudinal axis of the injector during the fuel injection phase of the injection cycle is minimized.

THE EMBODIMENT SHOWN IN FIGS. 7-13

In FIGS. 7-13, inclusive, another fuel injector em-

bodying the features of the present invention is illustrated. Many of the parts of the injector shown in these figures are identical with those of the injector shown in FIG. 1, and therefore have been given the same reference numerals as those of the corresponding parts in FIG. 1.

The injector shown in FIGS. 7-13, inclusive, comprises an elongated injector body 221 which, in the present instance, is of a multiple-piece construction so that replacement of the parts thereof which are subject to wear or other reason for renewal is facilitated. However, a unitary or one-piece construction could be utilized, if desired. The injector body 221 thus includes a generally cylindrical body member 222, a nozzle member 103 and a pair of generally cylindrical, upper and lower spacer members 224 and 105, respectively, located between the body member 222 and nozzle member 103. The nozzle member 103 and spacer members 224 and 105 are arranged and held in end-to-end relation by a tubular retainer 106.

The nozzle member 103 has a fuel injection chamber 143 therein provided by a cavity adjacent the lower end of the nozzle member, and the inner ends of a plurality of minute, circumferentially spaced, generally radially extending holes 157 in the lower end of the nozzle member communicate with the chamber 143 below a valve seat 166 therein. The outer ends of the holes 157 open into the cylinder with which the injector is associated. The communication between the holes 157 and chamber 143 is controlled by a valve member 158 shiftably mounted in an axial bore 160 in the nozzle member, the lower end, indicated at 164, of the valve member 158 being urged toward the seat 166 in the chamber 143 by a coil spring 172 mounted in a cavity 173 in the spacer member 105. The upper end of the cavity 173 is closed by the spacer member 104.

The nozzle member 103, spacer member 105, and retainer 106 of the injector shown in FIG. 7, the bores and passages therein, as well as the other parts in the lower portion of the injector, are identical in construction and operation with their like-numbered parts in the injector shown in FIG. 1. Consequently, no detailed description of these parts of the injector of FIG. 7 will be included.

The injector body member 222 has a central, axial bore 225 therethrough in which a plunger 226 is reciprocably mounted. The plunger 226 comprises a control portion 227 and a sleeve portion 118 secured to the upper end of the control portion 227. The sleeve portion 118 of the plunger 226, as well as the other parts at the upper end of the injector shown in FIG. 7, are likewise identical in construction and operation with the corresponding parts in the injector shown in FIG. 1, and therefore no further description of these parts will be included.

As heretofore mentioned, the injector body 221 includes variable volume chamber means for receiving a quantity of fuel from a source thereof under variable pressure, and a fuel supply passage 230 having one end connected to the variable volume chamber means and its other end adapted to be connected to said source. The other end of the fuel supply passage 230, in the present instance, includes a circumferential groove 131 in the outer surface of the body member 222, the groove 131 being adapted to register with an associated fuel supply bore or rail (not shown) in the cylinder head of the engine when the injector body 221 is seated

in the cylinder head. A transverse bore 132 extends inwardly from the groove 131 and a plug 133 (FIG. 1) having a balancing orifice 134 therethrough is threaded into the outer end of the bore 132. A filtering screen assembly 136 may be mounted in the groove 131 around the plug 133. The balancing orifice 134 and filtering screen assembly 136 of the injector of FIG. 7 perform the same functions as the balancing orifice 134 and filtering screen assembly 136 of the injector of FIG. 1.

The inner end of the transverse bore 132 communicates with the upper end of a longitudinal bore 234 in the body member 222 and the lower end of the longitudinal bore 234 is closed, as by a plug 235. The longitudinal bore 234 intermediate its length is intersected by another transverse bore 237 in the body member 222, the inner end, indicated at 238, of the transverse bore 237 opening into the plunger bore 225 and the outer end of the transverse bore 237 being closed as by a plug 239. The inner end 238 of the transverse bore 237 comprises one end of the fuel supply passage 230.

The aforementioned variable volume chamber means is in two parts and comprises a receiving chamber 240 and the fuel injection chamber 143. The receiving chamber 240, in the present instance, constitutes the portion of the plunger bore 225 between the lower end face, indicated at 241, of the control portion 227 of the plunger 226 and the upper end face, indicated at 242, of a generally cylindrical piston 243 that is loosely fitted in the plunger bore 225. The clearance between the piston 243 and plunger bore 225 is exaggerated for clarity of illustration.

In order to provide a connection between the receiving chamber 240 and the fuel injection chamber 143, a connecting passage, indicated generally at 245, is provided. The passage 245, in the present instance, comprises a transverse bore 246 (FIGS. 8, 10 and 12) in the body member 222, the inner end of the transverse bore 246, indicated at 247, opening into the plunger bore 225 at a point somewhat below the point where the inner end 238 of the transverse fuel supply bore 238 opens into the plunger bore. The outer end of the transverse bore 246 is closed as by a plug 248. The transverse bore 246 is intersected by a longitudinal bore 249 in the body member 222, the lower end of which registers with an annular groove 252 in the upper end face, indicated at 253, of the spacer member 224. A longitudinal bore 254 (FIGS. 7, 9 and 11) in the spacer member 224 connects the groove 252 with another groove 256 in the lower end face, indicated at 257, of the spacer member 224 and the groove 256 registers with the upper end of the longitudinal bore 151 in the spacer member 105. Thus, the transverse bore 246, the portion of the longitudinal bore 249 below the transverse bore 246, groove 252, longitudinal bores 254 and 151, and the bore 156 in the nozzle member 103 comprise the connecting passage 245 which connects the receiving chamber 240 with the fuel injection chamber 143 of the injector of FIG. 7.

As heretofore mentioned, the piston 243 of the injector shown in FIG. 7 is movable in the plunger bore 225 in response to movement of the plunger 226. Since the plunger 226 and piston 243 determine the volume of the receiving chamber 240 and since movement of the plunger 226 toward the piston 243 will reduce the volume of the receiving chamber 240 when the lower end face, indicated at 258, of the piston 243 is engaged with

the upper end face, indicated at 253, of the spacer member 224, the plunger 226 comprises fluid displacement means for reducing the volume of the receiving chamber 240.

When the lower part of the control portion 227 of the plunger 226 closes the inner end 238 of the fuel supply bore 237 on its downward stroke, fuel is confined in the receiving chamber 240 and the pressure therein and in the fuel injection chamber 143 is increased. The lower part of the control portion 227 thus comprises preventing means for preventing fuel from flowing from the receiving chamber through the supply passage 230 to the fuel supply rail or source.

Since the lower end face 241 of the control portion 227 of the plunger is one of the determinants of the volume of the receiving chamber 240 and since injection begins only after the lower end face 241 of the plunger 226 closes the inner end 238 of the fuel supply bore 237 and the lower end face 258 of the piston 243 has engaged the upper end face 253 of the spacer member 224, the maximum quantity of fuel that can be injected into the associated cylinder of the engine by the injector of FIG. 7 is limited. The upper end face 253 of the spacer member 224 thus defines one end of the plunger bore 225 and such end comprises a stop for limiting movement of the piston 243 in one direction.

In order to provide for free movement of the piston 243 in the plunger bore 225 and for free movement of the valve member 159 in its bore 160, a drain passage 30 is provided in the injector body 221 for connecting the part of the bore 225 below the lower end face 258 of the piston 243 and the valve spring cavity 173 to a drain or other low pressure zone, such as a drain rail in the engine cylinder head. Such drain passage, in the present instance, comprises an axial bore 262 through the spacer member 224 and having its upper end opening in the upper end face 253 of the spacer member 224 and its lower end opening into the valve spring cavity 173 in the lower portion of the injector body 221. A radial bore 207 in the spacer member 105 connects the cavity 173 with an annular groove 208 in the outer periphery of the spacer member 105. The groove 208 opens into an annular clearance 209 between the spacer members 224 and 105 and the retainer 105. The upper end of the clearance 209 is connected to the lower end of a longitudinal bore 212 in the injector body member 222, and the upper end of the bore 212 is connected to a slanting drain bore 193 in the body member 222. The outer end of the drain bore 193 opens into a circumferential groove 194 in the outer surface of the body member 222, and the groove 194 is adapted to register with the associated drain rail in the cylinder head of the engine. Thus, the drain passage of the injector of FIG. 7 comprises the axial bore 262, spring cavity 173, transverse bore 207, groove 208, clearance 209 between the spacer members 224 and 105 and retainer 106, longitudinal bore 212, slanting bore 193, and circumferential groove 194.

Injection of fuel into the engine cylinder occurs in a manner to be described hereafter in connection with the description of the operation of the injector.

The injector of FIG. 7 further includes pressure relief passage means, which comprises the portion of the longitudinal bore 249 above the transverse bore 246 and another transverse bore 263 (FIGS. 8, 10 and 12) in the body member 222 which intersects the upper end of the longitudinal bore 249. The inner end, indicated

at 264, of the transverse bore 263 opens into the plunger bore 225, and the outer end thereof may be closed as by a plug 266. Since the longitudinal bore 249 is connected to the receiving chamber 240 by the transverse bore 246 and since the receiving chamber 240 is connected to the fuel injection chamber 143 in the manner previously described, the transverse bore 263 is likewise connected to these chambers.

When the plunger 226 is approaching the end of its downward or fuel injection stroke, the inner end 264 of the transverse bore 263 is connected to a zone of reduced pressure, in this instance the drain bore 193. Such connection is provided by an annular reduced diameter portion 267 on the control portion 227 of the plunger, which defines an annular space 268 in the plunger bore 225 and which moves into communication with the inner end 264 of the transverse bore 263 as the plunger nears the end of its downward stroke. The inner end 192 of the slanting drain bore 193 is in continuous registry with the annular space 268 throughout the range of movement of the plunger 226.

When the inner end 264 of the transverse bore 263 is connected to the annular space 268, the pressure in the receiving chamber 240 and consequently in the fuel injection chamber 143 is relieved. As soon as the pressure in the fuel injection chamber 143 is relieved, the valve spring 172 shifts the valve member 158 downwardly until the lower end 164 thereof engages the seat 166. Seating of the lower end 164 of the valve member 158 terminates injection of fuel into the cylinder and the injection cycle of the injector of FIG. 7.

OPERATION OF THE EMBODIMENT SHOWN IN FIGS. 7-13

At the completion of an injection cycle of the injector shown in FIGS. 7-13, inclusive, and prior to the beginning of another cycle, the parts of the injector are in the positions shown in FIGS. 7 and 8. Thus, the lower end face 258 of the piston 243 will be engaged with the upper end face 253 of the spacer member 224 and the lower, full diameter part of the control portion 227 of the plunger 226 closes the inner end 238 of the fuel supply passage 230.

As the injection cycle begins, the plunger 226 moves upwardly in its bore 225. During the initial part of such movement and before the lower end face 241 of the control portion 227 of the plunger opens the inner end 238 of the fuel supply passage 230, the piston 243 will closely follow the lower end face 241 of the plunger 226 because of the suction created by upward movement of the plunger. The space in the plunger bore 225 below the piston 243 is connected to the drain rail in the cylinder head of the engine by the drain passage in the injector body 221. Such drain passage includes the axial bore 262 in the spacer member 224, spring cavity 173 and transverse bore 207 in the spacer member 105, annular clearance 209 between the spacer members 105 and 224 and the retainer 106, the longitudinal bore 212 and the slanting drain bore 193 and the circumferential groove 194 in the body member 222, which registers with the drain rail. During this portion of the injection cycle, fuel flows in a reverse direction through the aforementioned drain passage and into the space below the piston 243 as the latter moves upwardly in the plunger bore 225.

When the lower end face 241 of the plunger 226 opens the inner end 238 of the transverse fuel supply

bore 237, fuel from the fuel supply rail will flow into the receiving chamber 240 between the lower end face 241 of the plunger 226 and the upper end face 242 of the piston 243 and cause the piston to separate from the lower end face 241 of the plunger 226. Such flow continues during the remainder of the upward stroke of the plunger 226. The quantity of fuel supplied to the receiving chamber 240 depends upon the pressure of the fuel in the fuel supply rail. Thus, if the pressure of the fuel in the fuel supply rail is low, only a small amount of fuel will flow into the receiving chamber 240. Conversely, if the pressure of the fuel in the fuel supply rail is high, a comparatively large amount of fuel will flow into the receiving chamber 240.

On downward movement of the plunger 226, the lower end face 241 of the plunger closes the inner end 238 of the fuel supply bore 237 and confines fuel in the receiving chamber 240. Fuel in the plunger bore 225 below the piston 243 is displaced through the aforementioned drain passage and into the associated drain rail as the piston 243 moves downwardly.

Further downward movement of the plunger 226 causes the piston 243 to seat on the upper end face 253 of the spacer member 224 and seal the upper end of the bore 262 of the drain passage, if it has not already done so. When this occurs, the pressure in the receiving chamber 240 will rapidly rise. Such pressure rise is communicated through the connecting passage 245 to the fuel injection chamber 143 and, when the pressure reaches a predetermined value, the valve member 158 will move upwardly in its bore and the lower end 164 of the valve member 158 will lift off of its seat 166 as illustrated in FIG. 11. Consequently, fuel under pressure in the fuel injection chamber 143 will be injected through the nozzle holes 157 into the associated cylinder of the engine. The clearance shown in FIG. 11 between the lower end 164 of the valve member 158 and its seat 166 is exaggerated for clarity of illustration.

Injection of fuel through the nozzle holes 157 continues until the lower or control edge 269 of the reduced diameter portion 267 opens the inner end 264 of the transverse pressure relief bore 263 (FIG. 8) to the annular space 268. When this occurs, the pressure in the receiving chamber 240 and consequently in the fuel injection chamber 143 is immediately relieved due to the connection of these chambers with the aforementioned drain passage in the injector.

As soon as the pressure in the fuel injection chamber 143 is relieved, the spring 172 shifts the valve member 158 downwardly into engagement with the seat 166. Seating of the lower end 164 of the valve member 158 terminates injection of fuel into the cylinder and the injection cycle of the injector shown in FIG. 7.

55 THE EMBODIMENT SHOWN IN FIGS. 14-19

In FIGS. 14-19, inclusive, another fuel injector embodying the features of the present invention is illustrated. Many of the parts of the injector shown in these figures are identical with those of the injectors of the two previous embodiments and therefore have been given the same reference numerals as those of the corresponding parts in FIGS. 1 and 7. The injector of FIG. 14, however, is most similar in construction and operation to the injector of FIG. 7 and therefore only the differences in construction and operation of the injector of FIG. 14 from the injector of FIG. 7 will be hereinafter described in detail.

The injector shown in FIGS. 14-19, inclusive, comprises an elongated injector body 281 which, in the present instance, is of a multiple-piece construction so that replacement of the parts thereof which are subject to wear or other reason for renewal, is facilitated. However, a unitary or one-piece construction could be utilized, if desired. The injector body 281 includes a generally cylindrical body member 222, a nozzle member 103 and a pair of generally cylindrical, upper and lower spacer members 224 and 105, respectively, located between the body member 222 and nozzle member 103. The nozzle member 103 and spacer members 224 and 105 are arranged and held in end-to-end relation by a tubular retainer 106.

The nozzle member 103 has a fuel injection chamber 143 therein provided by a cavity adjacent the lower end of the nozzle member, and the inner ends of a plurality of minute, circumferentially spaced, generally radially extending holes 157 in the lower end of the nozzle member communicate with the chamber 143 below a valve seat 166 therein. The outer ends of the holes 157 open into the cylinder with which the injector is associated. The communication between the holes 157 and chamber 143 is controlled by a valve member 158 shiftably mounted in an axial bore 160 in the nozzle member, the lower end, indicated at 164, of the valve member 158 being urged toward the seat 166 in the chamber 143 by a coil spring 172 mounted in a cavity 173 in the spacer member 105. The upper end of the cavity 173 is closed by the spacer member 224.

The body member 222, nozzle member 103, spacer members 224 and 105, and retainer 106 of the injector shown in FIGS. 14-19, the bores and passages therein, and the other parts in the lower portion of the injector are identical with their like-numbered parts in the injectors of FIGS. 1 and 7. Consequently, no detailed description of these parts of the injector of FIG. 14 will be included.

The injector of FIG. 14 differs from the injector of FIG. 7 in that a portion of the fuel supply passage thereof, indicated generally at 285, is different, and the construction of the piston, indicated generally at 290, is also different.

The fuel supply passage 285 of the injector of FIG. 14 differs from the fuel supply passage 230 of the injector 220 in that the inlet portion of the transverse fuel supply bore, indicated at 132, is unrestricted, that is, no plug, such as the plug 133 of the injector of FIG. 7 having a balancing orifice 134 therethrough, is used. Thus, the fuel supply passage 285 of the injector of FIG. 14 presents a substantially unrestricted path to the flow of fuel into the injector from the associated fuel supply rail in the cylinder head of the engine in which the injector is mounted.

The piston 290 of the injector of FIG. 14 is similar to the piston 243 of the injector of FIG. 7 to the extent that the piston 290 is likewise generally cylindrical in form and is sized to loosely fit in the plunger bore 225. The clearance between the piston 290 and plunger bore 225 is exaggerated in FIGS. 14-18, inclusive for clarity of illustration.

The piston 290 differs from the piston 243 in that the piston 290 is hollow and has a metering spring 292 mounted therein. The spring 292 is of the coiled compression type and has its upper end engaging the inner surface of the end wall of the piston 290 and its lower

end engaging the upper end face 253 of the spacer member 224.

The injector of FIG. 14 is identical, in all other respects, with the injector of FIG. 7.

5 OPERATION OF THE EMBODIMENT SHOWN IN FIGS. 14-19

At the completion of an injection cycle of the injector shown in FIGS. 14-19, inclusive, and prior to the 10 beginning of another cycle, the parts of the injector are in the positions shown in FIGS. 14 and 15. Thus, the upper end face 242 of the piston 290 is held engaged with the lower end face 241 of the plunger 226 by the force of the metering spring 292. A slight clearance 15 may or may not be present between the lower end face 258 of the piston 290 and the upper end face 253 of the spacer member 224 at this time. In addition, the lower, full diameter part of the control portion 227 of the plunger 226 closes the inner end 238 of the fuel supply 20 passage 285.

As the injection cycle begins, the plunger 226 moves upwardly in its bore 225. During the initial part of such movement and before the lower end face 241 of the control portion 227 of the plunger opens the inner end 238 of the fuel supply bore 237, the piston 290 will be moved upwardly in the bore 225 by the force of the metering spring 292. At this time, the upper end face 242 of the piston 290 will be maintained in engagement with the lower end 241 of the plunger 226. Since upward movement of the plunger 226 and piston 290 create suction in the space or clearance below the lower end face 258 of the piston 290, fuel from the associated drain rail in the cylinder head of the engine will flow in a reverse direction through the drain passage into the space. The various bores and cavities in the injector body 281 which constitute the drain passage of the injector of FIG. 14 are the same as those of the injector of FIG. 7.

When the lower end face 241 of the plunger 226 40 opens the inner end 238 of the transverse fuel supply bore 237, fuel from the fuel supply rail will flow into the receiving chamber 240 and act upon the piston 290 and to oppose the force of the metering spring 292. The pressure in the receiving chamber 240 will be substantially the same as the pressure in the fuel supply rail due to the unrestricted character of the fuel supply passage 285. Thus, the piston 290 and the plunger 226 will be caused to separate by an amount proportional to the pressure of the fuel in the fuel supply passage 285. Such flow continues during the remainder of the upward stroke of the plunger 226.

The quantity of fuel supplied to the receiving chamber 240 depends substantially only upon the pressure of the fuel in the fuel supply rail. Thus, if the pressure of the fuel in the fuel supply rail is low, only a small amount of fuel will flow into the receiving chamber 240. Conversely, if the pressure of the fuel in the fuel supply rail is high, a comparatively large amount of fuel will flow into the receiving chamber 240.

On downward movement of the plunger 226, the lower end face 241 of the plunger closes the inner end 238 of the fuel supply bore 237 and confines fuel in the receiving chamber 240. Fuel in the plunger bore 225 below the piston 290 is displaced through the drain passage in the injector body 281 and into the associated drain rail, in the same manner as in the injector of FIG. 7.

Further downward movement of the plunger 226 causes the lower end face 258 of the piston 290 to seat on the upper end face 253 of the spacer member 224 and seal the upper end of the bore 262 of the drain passage, if it has not already done so. When this occurs, the pressure in the receiving chamber 240 rapidly rises. Such pressure rise is communicated through the passage means 245 to the fuel injection chamber 143. When the pressure in the fuel injection chamber 143 reaches a predetermined value, the valve member 158 will move upwardly in its bore 159 and the lower end 164 of the valve member will lift off of its seat 166 as illustrated in FIG. 17. Consequently, fuel under pressure in the fuel injection chamber 143 will be injected through the nozzle holes 157 into the associated cylinder of the engine. The clearance shown in FIG. 17 between the lower end 164 of the valve member 158 and its seat 166 is exaggerated for clarity of illustration.

Injection of fuel through the nozzle holes 157 continues until the lower or control edge 269 of the reduced diameter portion 267 opens the inner end 264 of the transverse pressure relief bore 263 (FIG. 18) to the annular space 268. When this occurs, the pressure in the receiving chamber 240 and the pressure in the fuel injection chamber 143 is immediately relieved due to the connection of these chambers with the aforementioned drain passage in the injector. As soon as the pressure in the fuel injection chamber 143 is relieved, the spring 172 shifts the valve member 158 downwardly into engagement with the seat 166. Seating of the lower end 164 of the valve member 158 terminates injection of fuel into the cylinder and the injection cycle of the injector.

As in the injector illustrated in FIG. 7, since the lower end face 241 of the plunger 226 of the injector of FIG. 14 is one of the determinants of the volume of the receiving chamber 240 and since injection of fuel begins only after the lower end face 241 of the plunger closes the inner end 238 of the fuel supply bore 237 and the lower end face 258 of the piston 243 has engaged the upper end face 223 of spacer member 224, the maximum quantity of fuel that can be injected by the injector of FIG. 14 is limited.

Thus, the injector illustrated in FIG. 14 may be characterized as a "pressure controlled" injector in that, due to the unrestricted character of the fuel supply passage 285 thereof, the quantity of fuel supplied to the receiving chamber 240 and consequently the quantity of fuel injected into the associated cylinder of the engine is determined substantially only by the pressure of the fuel in the associated fuel supply rail.

THE EMBODIMENT SHOWN IN FIGS 20-25

In FIGS. 20-25, inclusive, another fuel injector embodying the features of the present invention is illustrated. Many of the parts of the injector shown in these figures are identical with those of the injector shown in FIG. 1 and therefore have been given the same reference numerals as those of the corresponding parts in FIG. 1. Therefore only the differences in construction and operation of the injector of FIG. 20 from the injector of FIG. 1 will be hereinafter described in detail.

The injector shown in FIGS. 20-25, inclusive, comprises an elongated injector body 301 which, in the present instance, is of a multiple-piece construction so that replacement of the parts thereof which are subject to wear or other reason for renewal, is facilitated. How-

ever, a unitary or one-piece construction could be utilized, if desired. The injector body 301 includes a generally cylindrical body member 302, a nozzle member 103 and a pair of generally cylindrical, upper and lower spacer members 304 and 105, respectively, located between the body member 302 and nozzle member 103. The nozzle member 103 and spacer members 304 and 105 are arranged and held in end-to-end relation by a tubular retainer 106.

The nozzle member 103 has a fuel injection chamber 143 therein provided by a cavity adjacent the lower end of the nozzle member, and the inner ends of a plurality of minute, circumferentially spaced, generally radially extending holes 157 in the lower end of the nozzle member communicate with the chamber 143 below a valve seat 166 therein. The outer ends of the holes 157 open into the cylinder with which the injector is associated. The communication between the holes 157 and chamber 143 is controlled by a valve member 158 shiftably mounted in an axial bore 160 in the nozzle member, the lower end, indicated at 164, of the valve member 158 being urged toward the seat 166 in the chamber 143 by a coil spring 172 mounted in a cavity 173 in the spacer member 105. The upper end of the cavity 173 is closed by the spacer member 304.

The spacer member 105, nozzle member 103, retainer 106, and the bores and passages therein, as well as the other parts in the lower portion of the injector body 301 are identical with their like-numbered parts 30 in the injector of FIG. 1. Consequently, no detailed description of these parts of the injector of FIG. 20 will be included.

The injector body member 302 has a central, axial bore 305 therethrough in which a plunger 306 is reciprocably mounted. The plunger 306 comprises a control portion 307 and a sleeve portion 118 secured to the upper end of the control portion 307. The sleeve portion 118 of the plunger 306, as well as the other parts at the upper end of the injector shown in FIG. 20, are identical in construction and operation with the corresponding parts of the injector shown in FIG. 1 and therefore no further description of these parts will be included.

The injector of FIG. 20 differs from the injector of FIG. 1 primarily in the construction of the fuel supply passage thereof, and also in the construction of the upper spacer member 304. Thus, the fuel supply passage of the injector of FIG. 20, which is indicated generally at 310, has one end connected to a variable volume chamber means in the injector body 301 and its other end adapted to be connected to a source of fuel under variable pressure. The other end of the fuel supply passage 310 is provided by a circumferential groove 131 in the outer surface of the injector body member 302, the groove 131 being adapted to register with an associated fuel supply bore or rail in the cylinder head of the engine.

The fuel supply passage 310 also includes a transverse bore 132 which extends inwardly from the groove 131, and a plug 133 having a balancing orifice 134 therethrough is threaded into the outer end of the transverse bore 132. A filtering screen assembly 136 may be mounted in the groove 131 around the plug 133. The balancing orifice 134 and filtering screen assembly 136 of the injector of FIG. 20 perform the same functions as the balancing orifice 134 and filtering screen assembly 136 of the injector of FIG. 1, that is,

the balancing orifice 134 restricts and meters the flow of fuel through the fuel supply passage 310 and the filtering screen assembly 136 prevents foreign particles from entering the fuel supply passage.

The inner end of the transverse bore 132 intersects the upper end of a longitudinal bore 137 in the body member 302, and the lower end of the longitudinal bore 137 is closed as by a plug 312. The longitudinal bore 137 is intersected intermediate its length by another transverse bore 313 in the injector body member 302 below the transverse bore 132. The inner end, indicated at 314, of the transverse bore 313 opens in the plunger bore 305 and the outer end thereof is closed as by a plug 315.

The fuel supply passage 310 further includes a circumferential groove 316 in the lower part of the control portion 307 of the plunger 306, the groove 316 being cyclically movable into and out of registry with the inner end 314 of the transverse bore 313 and with the inner end, indicated at 317 (FIGS. 21 and 24), of another transverse bore 318 in the injector body member 302. The inner end 317 of the transverse bore 318 opens into the plunger bore 305 and the outer end of the bore 318 is closed as by a plug 319 (FIG. 21). In this instance, the transverse bore 318 is at a right angle to the bore 313. The transverse bore 318 intersects a longitudinal bore 320 (FIGS. 21, 24 and 25) in the body member 302, the lower end of the bore 320 communicating with a circular cavity or recess 141 in the upper end face of the spacer member 304. The lower end of the plunger bore 305 opens into the cavity 141.

As in the previously described embodiments, the injector of FIG. 20 includes variable volume chamber means. Such variable volume chamber means, in the present instance, is in two parts and comprises a receiving chamber 321 and a fuel injection chamber 143 connected to the receiving chamber 321 by a connecting passage, indicated generally at 322, in the lower end of the injector body 301. The receiving chamber 321, in the present instance, constitutes the cavity 141 and the portion of the plunger bore 305 below a piston in the form of a ball 144 loosely fitted in the plunger bore 305 below the lower end face, indicated at 323, of the control portion 307 of the plunger 306. Since the ball 144 determines the volume of the receiving chamber and is movable in response to movement of the plunger 306, the plunger and ball 144 comprise fluid displacement means for reducing the volume of the receiving chamber 321 and for increasing the pressure therein and in the fuel injection chamber 143. Moreover, the full diameter part of the control portion 307 above the groove 316 comprises preventing means for preventing fuel from flowing from the receiving chamber 321 through the fuel supply passage 310 to the fuel supply rail when fuel is being injected into the cylinder.

In addition, since the volume of the receiving chamber 321 is determined by the ball 144 and since the volume of the receiving chamber 321 will be at a maximum when the ball 144 is engaged with the end face 323 of the plunger when the latter is at the end of its upward stroke, the end face 323 of the plunger comprises a stop limiting movement of the ball 144 in one direction and the volume of the receiving chamber 321 to a predetermined maximum.

The connecting passage 322, in the present instance, comprises at least one longitudinal bore 324 in the upper spacer member 304. The upper end of the bore

324 extends downwardly from the cavity 141, and the lower end of the longitudinal bore 324 intersects an annular groove 150 in the lower end face of the spacer member 304. While only one longitudinal bore 324 is shown extending between the cavity 141 and annular groove 150 in the spacer member 304, an additional, diametrically spaced longitudinal bore could be provided in the spacer member 304, if desired.

Another longitudinal bore 151 is provided in the spacer member 105 and is located therein so that the upper end of the bore 151 registers with the annular groove 150 when the injector of FIG. 20 is assembled. The lower end of the longitudinal bore 151 may be counterbored as at 152 to define an annular seat 153, and a check ball 154 may be mounted in the counterbore 152 for engaging the seat 153. If so provided, the check ball 154 comprises preventing means for preventing gas or pressure waves from passing upwardly in the bore 151 from the fuel injection chamber 143 toward the balancing orifice 134 and into the associated fuel supply bore or rail in the cylinder head of the engine in the event of failure or malfunction of the injector.

The counterbore 152 registers with an annular groove 155 in the upper end face of the nozzle member 103, and a slanting bore 156 in the nozzle member 103 interconnects the groove 155 with the fuel injection chamber 143. Thus, the longitudinal bore 324 and annular groove 150 in the spacer member 304, longitudinal bore 151 in the spacer member 105, and slanting bore 156 in the nozzle member 103 comprise the connecting passage 322 which connects the receiving chamber 321 with the fuel injection chamber 143.

As previously mentioned, the injector of FIG. 20 also includes a drain passage which permits variation of the volume of the receiving chamber 321 and free movement of the valve member 158 in its bore 160. The drain passage of the injector of FIG. 20 connects the space, indicated at 326, between the ball 144 and the lower end face 323 of the plunger 306 with a drain or other low pressure zone, such as a drain rail in the engine cylinder head. Connection of the space 326 to the drain permits fuel to be freely drawn into the space 326 and thus prevents any substantial vacuum from being created in the space 326 during the upward stroke of the plunger 306 which would tend to cause the ball 144 to remain in contact with or closely follow the lower end face 323 of the plunger 306 on its upward stroke. Thus, the ball 144 of the injector of FIG. 20 is movable upwardly in the plunger bore 305 substantially only by the pressure of the fuel in the supply passage 310, as in the injector of FIG. 1.

The drain passage of the injector of FIG. 20 comprises an axial bore or duct 327 in the lower part of the control portion 307 of the plunger 306, the lower end, indicated at 328, of the duct 327 opening in the end face 323 of the plunger and being located so as to be closed by the ball 144 when the latter engages the end face 323.

The upper end of the duct 327 intersects a cross bore 332 in a reduced diameter portion 333 of the control portion 307 of the plunger, the reduced diameter portion 333 defining an annular space 334 in the plunger bore 305. The annular space 334 is in constant registry with the inner end, indicated at 192, of a bore 193 slanting upwardly and outwardly in the injector body member 302 from the plunger bore 305. The outer or

upper end of the bore 193 opens into a circumferential groove 194 in the outer surface of the injector body member 302, the groove 194 being adapted to communicate with the drain rail in the cylinder head of the engine. Thus, the space 326 above the ball 144 is connected to the drain so long as the lower end 328 of the duct 327 is not closed by the ball 144.

Injection of fuel into the engine cylinder occurs in a manner to be described hereafter in connection with the description of the operation of the injector.

The injector of FIG. 20 further includes pressure relief passage means, which comprises another transverse bore 342 (FIGS. 21 and 24) in the injector body member 302, located above the bore 318 and intersecting the upper end of the longitudinal bore 320. The inner end, indicated at 343, of the transverse bore 342 opens into the plunger bore 305 and the outer end thereof is closed as by a plug 344. Since the longitudinal bore 320 is connected to the receiving chamber 321 and the receiving chamber 321 is connected to the fuel injection chamber 143 in the manner previously described, the transverse bore 342 is likewise connected to both of these chambers. The inner end 343 of the transverse bore 342 is positioned to communicate with the annular space 334 as the plunger 306 nears the end of its downward or fuel injection stroke. Thus, the pressure in the fuel injection chamber 143 will be relieved when the lower shoulder or control edge, indicated at 346, of the reduced diameter portion 333 of the plunger opens the inner end 343 of the transverse bore 342. As soon as the pressure in the fuel injection chamber 143 is relieved, the valve spring 172 shifts the valve member 158 downwardly until the lower end 164 thereof engages the seat 166. Seating of the lower end 164 of the valve member 158 terminates injection of fuel into the cylinder and the injection cycle of the injector of FIG. 20.

In order to prevent restriction of movement of the valve member 158 due to the presence of fuel in the valve spring cavity 173, the cavity 173 is vented to drain. Such venting is provided by a radial bore 207 in the spacer member 105, which extends from the cavity 173 to an annular groove 208 in the outer periphery of the spacer member 105. The groove 208 opens into an annular clearance 209 between the spacer members 105 and 304 and the retainer 106. The upper end of the clearance 209 communicates with the lower end of a longitudinal bore 212 in the injector body member 302 and the upper end of the bore 212 intersects the drain bore 193 to complete the vent connection to drain.

OPERATION OF THE EMBODIMENT SHOWN IN FIGS. 20-25

At the completion of an injection cycle of the injector shown in FIGS. 20-25 and prior to the beginning of another cycle, the parts of the injector are in the positions shown in FIGS. 20 and 21. The inner end 314 of the fuel supply passage 310 is closed at this time by the control portion 307 of the plunger 306 and the ball 144 will thus rest on the bottom of the cavity 141.

As the injection cycle begins, the plunger 306 begins to move upwardly in its bore. During the initial part of such movement and before the groove 316 in the control portion 307 of the plunger 306 moves into registry with the inner ends 314 and 317 (FIGS. 20 and 21) of the transverse fuel supply bores 313 and 318, respectively, fuel will flow in a reverse direction from the

drain into the space 326 above the ball 144. Consequently, the ball 144 will remain substantially stationary in the plunger bore 305 at this time.

When the groove 316 moves into registry with the inner ends 314 and 317 of the transverse bores 313 and 318, fuel from the fuel supply rail will flow through the fuel supply passage 310 into the receiving chamber 321. If the pressure of the fuel in the associated fuel supply rail, and hence in the fuel supply passage 310, is relatively low, only a small amount of fuel will flow into the receiving chamber 321 and the ball 144 will therefore rise in the plunger bore 305 only a small distance. Conversely, if the pressure of the fuel in the fuel supply rail, and hence in the fuel supply passage 310, is relatively high, a large amount of fuel will flow into the receiving chamber 321 and the ball 144 will rise in the plunger bore 305 a greater distance.

On downward movement of the plunger 306, fuel will be forced out of space 326 above the ball 144 through the drain passage in the injector body 301 until the lower end face 323 of the plunger engages the ball 144 and the latter closes the lower end 328 of the axial bore 327 in the plunger 306. After the plunger has engaged the ball 144 and after the groove 316 has moved out of registry with the inner ends 314 and 317 of the bores 313 and 318 and the full diameter portion of the plunger has closed these bores, the pressure in the receiving chamber 321 will rapidly rise. A corresponding pressure rise will also occur in the fuel injection chamber 143 since the fuel injection chamber 143 is connected to the receiving chamber 321 by the connecting passage 322.

When the pressure in the fuel injection chamber 143 reaches a predetermined value sufficient to overcome the force of the coil spring 172, the valve member 158 will move upwardly in its bore and the lower end 164 thereof will lift off of its seat 166. Consequently, fuel under high pressure from the fuel injection chamber 143 will be injected through the nozzle holes 157 and into the associated cylinder of the engine. The clearance shown in FIG. 23 between the lower end 164 of the valve member 158 and its seat 166 is exaggerated for clarity of illustration.

Injection of fuel through the nozzle holes 157 continues as the plunger 306 continues to move downwardly in its bore until the lower or control edge 346 of the reduced diameter portion 333 of the plunger opens the inner end 343 of the pressure relief bore 342. When this occurs, the pressure of the fuel in the receiving chamber 321, and consequently in the fuel injection chamber 143, is immediately relieved. As soon as the pressure in the fuel injection chamber 143 is relieved, the spring 172 shifts the valve member 158 downwardly in its bore 160 and causes the lower end 164 thereof to engage its seat 166. Seating of the lower end 164 of the valve member 158 terminates injection of fuel into the cylinder and the injection cycle of the injector shown in FIG. 20.

THE EMBODIMENT SHOWN IN FIGS. 26-29

In FIGS. 26-29, inclusive, another fuel injector embodying the features of the present invention is illustrated. Many of the parts of the injector shown in these figures are identical with those of the injectors of FIGS. 1 and 20 and therefore have been given the same reference numerals as those of the corresponding parts in FIGS. 1 and 20.

The injector shown in FIGS. 26-29, inclusive, comprises an elongated injector body 361 which, in the present instance, is of a multiple-piece construction so that replacement of the parts thereof which are subject to wear or other reason for renewal, is facilitated. However, a unitary or one-piece construction could be utilized, if desired. The injector body 361 includes a generally cylindrical body member 362, a nozzle member 103, and a pair of generally cylindrical, upper and lower spacer members 304 and 105, respectively, located between the body member 362 and nozzle member 103. The nozzle member 103 and spacer members 304 and 105 are arranged and held in end-to-end relation by a tubular retainer 106.

The nozzle member 103 has a fuel injection chamber 143 therein provided by a cavity adjacent the lower end of the nozzle member, and the inner ends of a plurality of minute, circumferentially spaced, generally radially extending holes 157 in the lower end of the nozzle member communicate with the chamber 143 below a valve seat 166 therein. The outer ends of the holes 157 open into the cylinder with which the injector is associated. Communication between the holes 157 and chamber 143 is controlled by a valve member 158 shiftably mounted in an axial bore 160 in the nozzle member, the lower end, indicated at 164, of the valve member 158 being urged toward the seat 166 in the chamber 143 by a coil spring 172 mounted in a cavity 173 in the spacer member 105. The upper end of the cavity 173 is closed by the spacer member 304.

The spacer members 304 and 105, nozzle member 103, and retainer 106 of the injector shown in FIGS. 26-29, the bores and passages therein, and the other parts of the lower portion of the injector are identical with their like-numbered parts in the injector of FIG. 20. Consequently, no detailed description of these parts of the injector of FIG. 26 will be included.

The injector body member 362 has a central, axial bore 363 therethrough in which a plunger 366 is reciprocably mounted. The plunger 366 comprises a control portion 367 and a sleeve portion 118 secured to the upper end of the control portion 367. The sleeve portion 118 as well as the other parts at the upper end of the injector shown in FIG. 26 are identical in construction and operation with the corresponding parts of the injector shown in FIG. 1, and therefore no further description of these parts will be included.

The injector of FIG. 26 differs from the injectors of FIGS. 1 and 20 primarily in the construction of the fuel receiving chamber of the variable volume chamber means therein, and also in the construction of the fuel supply and return passages. Thus, the fuel supply passage of the injector of FIG. 26, which is indicated generally at 370, has one end connected to the variable volume chamber means in the injector body 361 and its other end adapted to be connected to a source of fuel under variable pressure. Said other end of the fuel supply passage 370 is provided by a circumferential groove 131 in the outer surface of the injector body member 362, the groove 131 being adapted to register with an associated fuel supply bore or rail in the cylinder head of the engine.

The fuel supply passage 370 also includes a transverse bore 132 which extends inwardly from the groove 131, and a plug 133 having a balancing orifice 134 therethrough is threaded into the outer end of the transverse bore 132. A filtering screen assembly 136

may be mounted in the groove 131 around the plug 133. The balancing orifice 134 and filtering screen assembly 136 of the injector of FIG. 26 perform the same functions as the balancing orifice 134 and filtering screen assembly 136 of the injectors of FIGS. 1 and 20, that is, the balancing orifice 134 restricts and meters the flow of fuel through the fuel supply passage 370 and the filtering screen assembly 136 prevents foreign particles from entering the fuel supply passage.

10 The inner end of the transverse bore 132 intersects the upper end of a longitudinal bore 137 in the body member 362, and the lower end of the longitudinal bore 137 is closed as by a plug 312. The longitudinal bore 137 is intersected intermediate its ends by another transverse bore 373 in the injector body member 362 below the transverse bore 132. The inner end, indicated at 374, of the transverse bore 373 opens into the plunger bore 363 and the outer end thereof is closed as by a plug 375. The inner end 374 of the transverse bore 20 373 comprises one end of the fuel supply passage 370.

25 The aforementioned variable volume chamber means is in two parts and, in the present instance, comprises the fuel injection chamber 143 connected to a receiving chamber by a connecting passage 322. The receiving chamber constitutes a space 376 in the plunger bore 363 below the lower end face, indicated at 378, of the control portion 367 of the plunger 366, and that portion 377 of another longitudinal bore 382 in the injector body member 362 below a piston in the form of a ball 383 shiftably mounted in the bore 382. The upper end of the bore 382 is connected to a drain, as will be described more fully hereafter. The lower end of the portion 377 opens into a circular cavity 141 in the upper surface of the spacer member 304 and the lower end of the plunger bore 363 also opens into the cavity 141 so that the space 376 and portion 377 of the receiving chamber are in free communication with each other. The lower, full diameter part of the control portion 367 of the plunger 366 comprises preventing means for preventing fuel from flowing from the space 376 of the receiving chamber through the fuel supply passage and into the associated fuel supply rail in the engine cylinder head during the fuel injection phase of the injection cycle.

30 40 45 The aforementioned connecting passage 322 which connects the space 376 of the receiving chamber with the fuel injection chamber 143 is provided by the same bores and passages that form the connecting passage 322 of the injector of FIG. 20, and therefore no further description of the connecting passage 322 of the injector of FIG. 26 will be included.

50 55 60 65 As heretofore mentioned, the ball 383 is mounted in the bore 382 in the injector body member 362. The diameter and length of the bore 382 is such that the volume of the portion 377 of the receiving chamber is less than the volume of the space 376. Thus, the ball 383 will always move to the upper end of its bore 382, regardless of the position of the ball 383 at the start of the downward or fuel injection stroke of the plunger 366. Upward movement of the ball 383 in its bore 382 is limited by a seat 384 provided by the beveled upper end of the bore 382. Since the plunger 366 and ball 383 determine the volume of the receiving chamber and since downward movement of the plunger 366 will reduce the volume of the receiving chamber after the ball 383 engages its seat 384, the plunger 366 comprises fluid displacement means for reducing the volume of the re-

ceiving chamber and increasing the pressure therein and in the fuel injection chamber 143.

Moreover, since the volume of the receiving chamber will be at a maximum when the ball 383 is engaged with its seat 384 and the plunger 366 is at the end of its upward stroke, the seat 384 comprises a stop for limiting movement of the ball toward the end of the bore 382 opposite from the end that is connected to the plunger bore 363 and thus the volume of the receiving chamber. Consequently, the maximum quantity of fuel that can be injected into the associated cylinder of the engine by the injector of FIG. 26 is also limited.

In order to provide for a variation of the volume of the receiving chamber and hence variation of the quantity of fuel injected by the injector of FIG. 26 as a function of the pressure of the fuel in the fuel supply rail, a drain passage is provided in the injector. Such drain passage comprises a longitudinal bore 386 in the injector body member 362 which, in the present instance, is smaller in diameter than the bore 382 and extends coaxially therewith. Thus, the lower end of the longitudinal bore 386 is connected to the upper end of the longitudinal bore 382 and the upper end of the bore 386 intersects a bore 193 slanting upwardly and outwardly in the injector body member 362. The outer or upper end of the bore 193 opens into a circumferential groove 194 in the outer surface of the injector body member 362, the groove 194 being adapted to communicate with an associated drain rail in the cylinder head of the engine when the injector body 361 is seated in the cylinder head. Thus, the space in the longitudinal bore 382 above the ball 383 is at all times connected to the drain so that the ball 383 is free to move in the bore 382 in response to the pressure in the receiving chamber.

The injector of FIG. 26 further includes pressure relief passage means for relieving the pressure in the receiving chamber and fuel injection chamber 143 as the plunger 366 is approaching the end of its downward stroke, in order to assure positive termination of injection of fuel into the associated cylinder. Such pressure relief passage means comprises a transverse bore 388 in the injector body member 362, which intersects the plunger bore 363 and the longitudinal bore 382 below the ball 383 when the latter is engaged with its seat 384.

The outer end of the bore 388 is closed, as by a plug 389, and the inner end, indicated at 393, of the transverse bore 388 communicates with an annular space 394 in the plunger bore 363 provided by a reduced diameter portion 396 on the control portion 367 of the plunger 366 as the plunger nears the end of its downward stroke. The annular space 394 is in continuous registry with the inner end, indicated at 192, of the drain bore 193 throughout the range of movement of the plunger 366. Thus, the pressure in the fuel injection chamber 143 will be relieved when the lower or control edge, indicated at 397, of the reduced diameter portion 396 opens the inner end 393 of the pressure relief bore 388. Relief of pressure in the fuel injection chamber 143 permits the spring 172 to seat the valve member 158 and positively terminate injection of fuel into the cylinder.

In order to prevent restriction of movement of the valve member 158 due to the presence of fuel in the valve spring cavity 173, the cavity 173 is vented to drain. Such venting is provided by a radial bore 207 in the spacer member 105, which extends from the cavity

173 to an annular groove 208 in the outer periphery of the spacer member 105. The groove 208 opens into an annular clearance 209 between the spacer members 105 and 304 and the retainer 106. The upper end of the clearance 209 communicates with the lower end of a longitudinal bore 398 in the injector body member 362, and the upper end of the bore 398 intersects the inner end of a radial bore 399 in the body member. The outer end of the radial bore 399 opens into the circumferential groove 194 which communicates with the drain rail in the engine cylinder head, as previously described.

OPERATION OF THE EMBODIMENT SHOWN IN FIGS. 26-29

15 At the completion of an injection cycle of the injector shown in FIGS. 26-29 and prior to the beginning of another cycle, the parts of the injector are in the positions shown in FIG. 26. Thus, the ball 383 will be at the upper end of the longitudinal bore 382 and may be engaged with the seat 384 or may be positioned slightly below the seat. In addition, the inner end 374 of the transverse fuel supply passage 370 is closed at this time by the lower part of the control portion 367 of the plunger 366. Consequently, fuel under pressure from the fuel supply rail is prevented from acting on the ball 383.

As the injection cycle begins, the plunger 366 begins to move upwardly in its bore. During the initial part of such movement and before the lower end face 378 of the plunger 366 opens the inner end 374 of the transverse fuel supply bore 373, fuel will flow in a reverse direction from the drain rail through the drain passage comprising the circumferential groove 194, the slanting bore 193, and the longitudinal bore 386, into the upper end of the bore 382 above the ball 383. Consequently, the ball 383 will move downwardly in its bore 382 toward the lower end of the bore due to the transfer of fuel from the portion 377 of the receiving chamber into the space 376 thereof. Such fuel transfer results from suction in the space 376 caused by upward movement of the plunger 366.

When the lower end face 378 of the plunger opens the inner end 374 of the fuel supply bore 373, fuel from the fuel supply rail will flow into the space 376 and portion 377 of the receiving chamber. Consequently, the ball 383 will move upwardly in its bore 382. The extent to which the ball 383 rises in its bore 382 depends upon the quantity of fuel flowing into the portion 377 of the receiving chamber, and such quantity depends upon the pressure of the fuel in the associated fuel supply rail.

When the plunger 366 reaches the end of its upward stroke, the volume of the receiving chamber will be at a maximum if the pressure of the fuel in the supply rail is great enough to cause the ball 383 to engage its seat 384. However, if the pressure in the supply rail has been less, the ball 383 will be spaced below the seat 384, as shown in FIG. 27, and the volume of the receiving chamber will be less than maximum. The latter condition usually occurs when an engine utilizing injectors of the character shown in FIG. 26, is operating at less than its maximum power output.

On downward movement of the plunger 366, the lower end face 378 of the plunger closes the inner end 374 of the fuel supply bore 373 and thus shuts off the flow of fuel into the space 376 of the receiving chamber. Continued downward movement of the plunger

366 after the plunger has shut off the flow into the space 376 causes fuel to be transferred from the space 376 into the portion 377 of the receiving chamber. Consequently, the ball 383 will continue to move upwardly in its bore 382 toward its seat 384.

Further downward movement of the plunger 366 causes the ball 383 to engage its seat 384 and seal the upper end of the bore 382. When this occurs, the pressure of the fuel in the receiving chamber will rapidly rise. Such pressure rise is communicated through the connecting passage 322 to the fuel injection chamber 143 and, when the pressure reaches a predetermined value sufficient to overcome the force of the spring 172, the valve member 158 will lift off of its seat 166, as illustrated in FIG. 28, and open the nozzle holes 157. Consequently, fuel under pressure in the fuel injection chamber 143 will be injected through the nozzle holes 157 into the associated cylinder of the engine. The clearance shown in FIG. 28 between the lower end 164 of the valve member 158 and its seat 166 is exaggerated for clarity of illustration.

Injection of fuel through the nozzle holes 157 continues until the lower or control edge 397 of the reduced diameter portion 396 of the plunger opens the inner end 393 of the transverse pressure relief bore 388. When this occurs, the pressure in the receiving chamber and consequently in the fuel injection chamber 143 is immediately relieved due to the connection of these chambers with the aforementioned drain passage in the injector.

As soon as the pressure in the fuel injection chamber 143 is relieved, the spring 172 shifts the valve member 158 downwardly into engagement with its seat 166. Seating of the lower end 164 of the valve member 158 terminates injection of fuel into the cylinder and the injection cycle of the injector shown in FIG. 26.

THE EMBODIMENT SHOWN IN FIGS. 30-33

In FIGS. 30-33, inclusive, another fuel injector embodying the features of the present invention, is illustrated. This injector differs from the previous embodiments in that it is particularly adapted for use in an engine in which there is less than the usual amount of space between the valve seats and valve ports. Thus, the components of the injector of FIG. 30 are reduced in size and number and are confined in the upper portion of the injector body with the diameter of the lower portion of the injector substantially reduced. Consequently, the injector of FIG. 30 may be mounted in an engine cylinder head of the foregoing character without interfering with the larger valve seats and ports.

The injector shown in FIGS. 30-33 comprises an elongated injector body 401 which, in the present instance, is of a multiple-piece construction so that replacement of the parts thereof which are subject to wear or other reason for renewal, is facilitated. However, a unitary or one-piece construction could be utilized, if desired. The injector body 401 includes a generally cylindrical body member 402, a nozzle member 403, and a generally cylindrical spacer member 404 located between the body member 402 and nozzle member 403. The body member 402, nozzle member 403, and spacer member 404 are mounted in a generally cylindrical tubular retainer 406 and are held in end-to-end relation by the retainer. To this end, the retainer 406 is internally threaded as at 408, and the upper end of body member 402 is externally threaded as at 409 to

permit the body member 402 to be inserted into or removed from the retainer 406. To facilitate such insertion or removal, a pair of diametrically spaced axial bores 410 may be provided in the upper end face of the body member 402 for receiving a spanner wrench (not shown).

The nozzle member 403 is held in the retainer 406 by an annular, radially inwardly extending flange 412 at the lower end of the retainer, the flange 412 being adapted to engage an annular, radially outwardly extending flange 413 at the upper end of the nozzle member 403. Thus, when the flange 413 of the nozzle member 403 is engaged with the flange 412 at the lower end of the retainer 406, the spacer member 404 is clamped between the nozzle member 403 and the body member 402 in the manner illustrated in FIG. 30, and the nozzle member 403, spacer member 404, and body member 402 are held in abutting, end-to-end relation.

The body member 402 has a central axial bore 414 therethrough in which a plunger 416 is reciprocably mounted. The plunger 416 comprises a lower or control portion 417 and an upper sleeve portion 418 (FIG. 3) secured to the upper end of the control portion 417. The sleeve portion 418 as well as the other parts at the upper end of the injector shown in FIG. 30 are similar in construction and operation to the corresponding parts of the injector shown in FIG. 1 and therefore no further description of these parts will be included.

The injector body 401 includes variable volume chamber means for receiving a quantity of fuel from a source thereof under variable pressure through a fuel supply passage, indicated generally at 430, having one end connected to the variable volume chamber means and the other end thereof adapted to be connected to said source. Said other end of the fuel supply passage 430, in the present instance, is provided by a circumferential groove 431 in the outer surface of the retainer 406, the groove 431 being adapted to register with an associated fuel supply bore or rail (not shown) in the cylinder head of the engine.

A transverse bore 432 in the side wall of the tubular retainer 406 extends inwardly from the groove 431 and a plug 433 having a balancing orifice 434 therethrough is threaded into the bore 432. The balancing orifice 434 serves to restrict and meter the flow of fuel into the fuel supply passage 430 and a filtering screen assembly 436 may be mounted in the groove 431 around the plug 433 to prevent foreign particles from entering the fuel supply passage 430.

After passing through the balancing orifice 434, fuel flows into a circumferential groove 436 in the outer surface of the body member 402, the groove 436 being positioned to register with the bore 432. From the groove 436, fuel flows into a transverse bore 437, which extends radially inwardly from the groove 436. From the bore 437 the fuel flow downwardly through a short longitudinal bore 438 in the body member 402. The lower end of the longitudinal bore 438 is counter-bored as at 439 to define an annular seat 440 for a check ball 441 mounted in the counterbore 439. The check ball 441 comprises preventing means for preventing fuel from flowing out of a receiving chamber in the injector body 401, to be hereinafter described in detail, and in a reverse direction through the fuel supply passage 430 into the associated fuel supply rail in the engine cylinder head during the fuel injection phase of the injection cycle. The lower end of the counter-

bore 439 communicates with an annular groove 442 in the upper end face of the spacer member 404 and a radially extending groove 443 in the lower end face of the body member 402 connects the groove 442 with the lower end of the plunger bore 414.

Thus, the fuel supply passage 430 comprises the circumferential groove 431, balancing orifice 434, transverse bore 432, circumferential groove 436, transverse bore 437, longitudinal bore 438, counterbore 439, annular groove 442, and radial groove 443 in the lower end face of the body member 402.

The aforementioned variable volume chamber means of the injector of FIG. 30 is in two parts and comprises a receiving chamber 452 and a fuel injection chamber. The receiving chamber 452, in the present instance, constitutes the portion of the plunger bore 414 below a piston in the form of a ball 454 loosely fitted in the plunger bore 414 below the lower end face, indicated at 455, of the control portion 417 of the plunger 416. The fuel injection chamber is defined by a cavity 453 in the nozzle member 403, and an elongated annular space 451 connected to and extending downwardly from the cavity 453, as will be described more fully hereafter.

In order to provide a connection between the receiving chamber 452 and the fuel injection chamber, a connecting passage, indicated generally at 456, is provided. The connecting passage 456 comprises at least one longitudinal bore 457 in the spacer member 404, the bore 457 extending from the groove 442 downwardly to intersect an annular groove 460 in the upper end face of the nozzle member 403. A slanting bore 461 in the nozzle member 403 connects the groove 460 with the cavity 453.

As previously mentioned, the injector of FIG. 30 is adapted for use with an engine cylinder wherein the valve seats and ports are closer together than usual so that less room is available between the seats and ports. To this end, the lower portion, indicated at 462, of the nozzle member 403 is elongated. Such structural configuration permits the injector of FIG. 30 to be mounted in an engine cylinder head which could not accommodate an injector of conventional shape.

The variable volume chamber means of the injector of FIG. 30 also includes an opening adapted to communicate with the cylinder of the engine with which the injector is associated and through which fuel is injected into the cylinder. In the present instance, such opening comprises a plurality of minute, circumferentially spaced, generally radially extending holes 463 in the lower end of the elongated portion 462 of the nozzle member 403, the inner ends of the holes 463 being adapted to be placed in communication with the annular portion 451 of the fuel injection chamber during the fuel injection phase of the fuel injection cycle.

Opening and closing of the holes 463 is controlled by a valve member. Such valve member is indicated generally at 468 and includes a valve body 469 shiftably mounted in an axial bore 470 in the nozzle member 403 in close-fitting relation. The valve member 468 also includes an elongated, stem portion 471 which is smaller in diameter than the inside diameter of the lower portion 462 of the nozzle member 403, to provide the annular portion 451 of the fuel injection chamber. The stem portion 471 also defines a shoulder or fluid pressure reaction surface 473 on the valve body 469, upon which the pressure in the fuel injection chamber acts.

The lower end of the stem portion 471 is tapered as at 474 for engagement with a complementally shaped seat 476 at the lower end of the nozzle member 403. The inner ends of the holes 463 open into a depression 5 below the seat 476 in the nozzle member 403. Thus, fuel from the fuel injection chamber is prevented from flowing through the holes 463 into the cylinder when the tapered lower end 474 of the stem portion 472 is engaged with its seat 476.

10 The lower end 474 of the stem portion 471 is normally urged toward its seat 476 by a coil spring 482 mounted in a cavity 483 in the spacer member 404. The upper end of the spring 482 engages the upper end of the cavity 483 and the lower end of the spring 482 15 engages an abutment in the form of a circular plate 484 at the lower end of the cavity 483. The lower face of the plate 484 is centrally recessed to receive the upper end of an extension 487 on the upper end of the valve body 469. The spring 482 is precompressed and holds the lower end 474 of the valve member 468 engaged with its seat 476 until a predetermined pressure occurs 20 in the fuel injection chamber.

As heretofore mentioned, a piston in the form of the ball 454 is mounted in the plunger bore 414 between the lower end face 455 of the plunger and the upper end face of the spacer member 404. The ball 454 is loosely fitted in the plunger bore 414 and is movable in response to movement of the plunger. Since the ball 454 determines the volume of the receiving chamber 25 452 and is movable in response to movement of the plunger 416, the plunger 416 and ball 454 comprise fluid displacement means for reducing the volume of the receiving chamber 452 and for increasing the pressure therein and in the fuel injection chamber.

30 35 In addition, since the volume of the receiving chamber 452 is determined by the ball 454 and since the volume of the receiving chamber 452 will be at a maximum when the ball 454 is engaged with the end face 455 of the plunger and the latter is at the upper end of its stroke, the end face 455 of the plunger comprises a stop limiting movement of the ball 454 in one direction and the volume of the receiving chamber 452 to a predetermined maximum. Consequently, the maximum 40 quantity of fuel that can be injected into the associated cylinder of the engine is also limited.

45 In order to provide for a variation of the volume of the receiving chamber 452, the space, indicated at 493, between the ball 454 and the lower end face 455 of the plunger 416 is connected to a drain or other low pressure zone, such as a drain rail in the engine cylinder head. Connection of the space 493 to the drain permits fuel to be freely drawn into the space 493 from the drain and thus prevents any substantial vacuum from being created in the space 493, which would tend to cause the ball 454 to remain in contact with or closely follow the lower end face 455 of the plunger during the upward stroke of the plunger. Thus, the extent of upward movement of the ball 454 in the plunger bore 414 50 55 is determined substantially only by the pressure of the fuel in the fuel supply passage 430 and this pressure is a direct function of the pressure of the fuel in the associated fuel supply rail in the engine cylinder head.

60 65 Connection of the space 493 above the ball 454 to the drain is provided by a drain passage having one end connected to the space 493 and its other end adapted to be connected to the drain. Such drain passage in the present instance, comprises an axial bore or duct 495

in the lower part of the control portion 417 of the plunger 416, the lower end, indicated at 496, of the duct opening in the end face 455 of the plunger and being located so as to be closed by the ball 454 when the latter engages the end face 455.

The upper end of the duct 495 intersects a cross bore 497 in a reduced diameter portion 498 of the control portion 417 of the plunger, the reduced diameter portion 498 defining an annular space 499 in the plunger bore 414. The annular space 499 is in continuous registry with the upper or inner end, indicated at 502, of a bore 503 slanting downwardly and outwardly in the injector body member 402 from the plunger bore 414. The outer or lower end of the slanting bore 503 opens into a circumferential groove 506 in the outer surface of the injector body member 402. An upwardly and outwardly slanting bore 507 in the side wall of the tubular retainer 406 connects the groove 506 with a circumferential groove 508 in the outer surface of the retainer, and the groove 508 is adapted to communicate with an associated drain bore or return rail in the engine cylinder head when the injector body 401 is seated in the cylinder head.

Injection of fuel into the engine cylinder occurs in the manner to be described hereinafter in connection with the description of the operation of the injector of FIG. 30.

The injector of FIG. 30 further includes pressure relief passage means for relieving the pressure in the receiving chamber 452 and fuel injection chamber as the plunger 416 is approaching the end of its downward stroke in order to assure positive termination of the injection of fuel into the associated cylinder. Such pressure relief passage means comprises a longitudinal bore 512 in the injector body member 402, which extends upwardly from the groove 443 in the body member 402. The upper end of the bore 512 intersects a transverse bore 513 in the body member and the inner end of the bore 513 opens into the plunger bore 414. The outer end of the bore 513 is closed as by a plug 514. Since the longitudinal bore 512 is connected to the receiving chamber 452 through the groove 443 and since the receiving chamber 452 is connected to the fuel injection chamber in the manner previously described, the transverse bore 513 is likewise connected to the fuel injection chamber.

The transverse bore 513 is axially positioned in the injector body member 402 so that the inner end thereof communicates with the annular space 499 in the plunger bore 414 when the plunger 416 is approaching the end of its downward or fuel injection stroke. Since the annular space 499 is at all times connected to the drain through the aforementioned drain passage, the pressure in the receiving chamber 452 and in the fuel injection chamber will be relieved whenever the lower or control edge, indicated at 516, of the reduced diameter portion 498 opens the inner end of the transverse bore 513 and vents such pressure to the drain. Relief of pressure in the fuel injection chamber permits the spring 482 to seat the valve member 468 and positively terminate injection of fuel into the cylinder.

In order to prevent restriction of movement of the valve member 468 due to the presence of fuel in the valve spring cavity 483, the cavity 483 is vented to the fuel supply passage 430. Such venting is provided by a radial bore 517 in the spacer member 404, which extends from the cavity 483 to a circumferential groove

518 in the outer periphery of the spacer member 404. The groove 518 opens into an annular clearance 520 between the spacer member 404 and tubular retainer 406. The clearance 520 extends up to and joins the groove 436 in the outer surface of the body member 402, the groove 436 comprising part of the fuel supply passage 430, as previously described. Thus, the interior of the valve spring cavity 483 is vented to the fuel supply passage 430 of the injector of FIG. 30. However, since during injection the pressure in the fuel injection chamber is many times greater than the highest pressure occurring in the fuel supply passage 430 and hence in the spring cavity 483, the force exerted by the pressure in the cavity 483 and tending to hold the valve member 468 seated is of no consequence.

OPERATION OF THE EMBODIMENT SHOWN IN FIGS. 30-33

At the completion of the injection cycle of the injector shown in FIGS. 30-33 and prior to the beginning of another cycle, the parts of the injector are in the positions shown in FIG. 30. Thus, fuel under pressure from the fuel supply passage 430 will flow into and through the receiving chamber 452 on its path to the drain rail in the engine cylinder head. Such path includes the radial groove 443, longitudinal bore 512, transverse bore 513, and annular space 499 which is part of the drain passage. Thus, fuel under pressure maintains the ball piston 454 in the plunger bore 414 engaged with the lower end face 455 of the plunger 416 so that the ball 454 closes the lower end 496 of the duct 495.

As the injection cycle begins, the plunger 416 begins to move upwardly in its bore. At this time, the receiving chamber 452 is connected to the drain passage through the radial groove 443, longitudinal bore 512, transverse bore 513, and annular space 499. During the initial part of the upward stroke of the plunger 416, the lower or control edge 516 of the reduced diameter portion 498 closes the inner end of the transverse pressure relief bore 513. Consequently, communication between the fuel receiving chamber 452 and the drain is cut off.

When the plunger 416 reaches the end of its upward stroke, the volume of the receiving chamber 452 will be at a maximum if the pressure of the fuel in the supply rail is then great enough to cause the ball 454 to engage the lower end face 455 of the plunger 416. However, if the pressure in the supply rail is less, the ball 454 will be spaced below the lower end face 455 of the plunger, as shown in FIG. 31, and the volume of the receiving chamber 454 will be less than maximum. The latter condition usually occurs when an engine utilizing injectors of the character shown in FIG. 30, is operating at less than its maximum power output.

Assuming that the pressure in the fuel supply rail has been insufficient to maintain the ball 454 engaged with the lower end face 455 of the plunger 416, as the plunger 416 begins its downward stroke fuel in the space 493 above the ball 454 will be forced upwardly through the duct 495 and then outwardly through the cross bore 497 into the annular space 499. From the space 499, the fuel proceeds to the drain. Such condition continues until the lower end face 455 of the plunger 416 contacts the ball 454 and the latter closes the lower end 496 of the duct 495, as illustrated in FIG. 32.

When the lower end face 455 of the plunger 116 contacts the ball 454 on its downward stroke and the

ball 454 closes the lower end 496 of the duct 495, continued downward movement of the plunger 416 will cause fuel to be displaced from the receiving chamber 452. Such displacement initially causes the check ball 441 to engage its seat 440 so that fuel is prevented from flowing in a reverse direction through the fuel supply passage 430 into the fuel supply rail. As soon as the check ball 441 seats, the pressure of the fuel in the receiving chamber 452, connecting passage 456 and fuel injection chamber, will rapidly rise. When the pressure acting on the reaction surface 473 of the valve member 468 reaches a predetermined value sufficient to overcome the force of the coil spring 482, the valve member 468 will move upwardly in its bore 470. Consequently, fuel under high pressure in the fuel injection chamber will be injected through the nozzle holes 463 and into the associated cylinder. The clearance shown in FIG. 32 between the lower end 474 of the valve member 468 and its seat 476 is exaggerated for clarity of illustration.

Injection continues until the control edge 516 of the reduced diameter portion 498 opens the inner end of the transverse pressure relief bore 513. When this occurs, pressure in the receiving chamber 452 and consequently in the fuel injection chamber, is immediately relieved. As soon as the pressure in the fuel injection chamber is relieved, the spring 482 shifts the valve member 468 downwardly in its bore 470 and causes the lower end 474 of the stem portion 471 to engage its seat 476. Seating of the lower end 474 of the valve member 468 terminates injection of fuel into the cylinder and the injection cycle of the injector shown in FIG. 30.

The elongated shape of the nozzle member 403 of the injector illustrated in FIG. 30 renders it particularly well suited for installation in the cylinder head of an engine wherein the valve seats and ports are too close to permit the use of an injector of conventional shape.

THE EMBODIMENT SHOWN IN FIGS. 34-36

In FIGS. 34-36, inclusive, another fuel injector embodying the features of the present invention is illustrated. This injector involves a novel arrangement for progressively increasing the force exerted by the spring tending to urge the valve member toward its seat during injection of fuel into the associated cylinder and the pressure of the fuel in the fuel injection chamber is increased to counteract the increased spring force. With the increased spring force, injection is rapidly and positively terminated at the completion of the injection cycle. Such arrangement reduces the possibility of combustion products entering the fuel supply passage of the injector and secondary injection.

The injector shown in FIGS. 34-36 comprises an elongated injector body 531 which, in the present instance, is of a multiple-piece construction so that replacement of the parts thereof which are subject to wear or other reason for renewal, is facilitated. However, a unitary or one-piece construction could be utilized, if desired.

The injector body 531 includes a generally cylindrical body member 532, a nozzle member 533 and a generally cylindrical spacer member 534 located between the body member 532 and the nozzle member 533. The nozzle member 533, spacer member 534 and body member 532 are arranged in end-to-end relation and are held in such relation by a tubular retainer 536. In

the present instance, the upper end, indicated at 537, of the retainer 536 is internally threaded, as at 540, to receive the threaded lower end, indicated at 541, of the body member 532. The lower end of the retainer 536 is provided with an internal flange 542 for engaging an annular, radially outwardly extending flange 543 on the nozzle member 533. Thus, when the retainer 536 is threaded onto the lower end 541 of the body member 532, as shown in FIG. 1, the body member 532, nozzle member 533 and spacer member 534 are held in abutting, end-to-end relation.

The injector body 531 has a central, axial bore therein, indicated generally at 544, for receiving an elongated plunger 546. The plunger 546 comprises a control portion 547 which closely fits a portion 548 of the plunger bore 544 in the spacer member 534, and a sleeve portion 552 which extends through another and somewhat larger portion 553 of the plunger bore 544. Thus, the sleeve portion 552 does not contact the wall 20 of the portion 553 of the plunger bore throughout the range of movement of the plunger.

The sleeve portion 552 as well as the other parts at the upper end of the injector shown in FIG. 34 are similar in construction and operation to the corresponding parts of the injector shown in FIG. 1 and therefore no further description of these parts will be included.

The injector body 531 includes variable volume chamber means for receiving a quantity of fuel from a source thereof under variable pressure through a fuel supply passage, indicated generally at 560, having one end connected to the variable volume chamber means and the other end thereof adapted to be connected to said source. Said other end of the fuel supply passage 560, in the present instance, includes a circumferential groove 561 (FIG. 34) in the outer surface of the body member 532, the groove 561 being adapted to register with an associated fuel supply rail (not shown) in the cylinder head of the engine. A transverse bore 562 extends inwardly from the groove 561 and a plug 563 having a balancing orifice 564 therethrough is threaded into the outer end of the bore 562. A filtering screen assembly 566 may be mounted in the groove 561 around the plug 563. The balancing orifice 564 and filtering screen assembly 566 of the injector of FIG. 34 perform the same functions as the balancing orifice 134 and filtering screen assembly 136 of the injector of FIG. 1, that is, the balancing orifice 564 restricts and meters the flow of fuel through the fuel supply passage 560 and the filtering screen assembly 566 prevents foreign particles from entering the fuel supply passage.

The inner end of the transverse bore 562 is intersected by the upper end of a longitudinal bore 567 in the injector body member 532 and the lower end of the longitudinal bore 567 is connected to the upper end of a longitudinal bore 568 in the spacer member 534. The lower end of the longitudinal bore 568 intersects a transverse bore 569 in the lower portion of the spacer member. The outer end of the transverse bore 569 is closed as by a plug 570, and the inner end, indicated at 571, opens into the portion 548 of the plunger bore 544 in the spacer member 534. The inner end 571 of the transverse bore 569 is reduced in diameter and comprises a feed hole through which fuel from the fuel supply passage 560 is supplied to the variable volume chamber means of the injector. In addition, the lower, full diameter part of the control portion 547 of the plunger 546 comprises preventing means for prevent-

ing fuel from flowing from a connecting passage, to be hereafter described in detail, in the injector body 531 and in reverse direction through the fuel supply passage 560 into the fuel supply rail in the engine cylinder head during the fuel injection phase of the injection cycle.

The aforementioned variable volume chamber means, in the present instance, is in two parts and comprises a fuel receiving chamber and a fuel injection chamber connected to the fuel receiving chamber by a connecting passage.

The fuel receiving chamber is indicated generally at 572 and comprises that portion of another longitudinal bore 574 in the spacer member 534 below a piston in the form of a ball 576 shiftably mounted in the bore 574. The upper end of the bore 574 is connected to a drain, as will be described more fully hereafter.

The fuel injection chamber is provided by a cavity 573 in the lower end of the nozzle member 533. Within the cavity 573 is a seat 578 which coacts with the lower end, indicated at 582, of a valve member 583 disposed in the fuel injection chamber 573. The manner in which the valve member 583 and its related structure is mounted in the lower portion of the injector body 531 will be described more fully hereafter.

As heretofore mentioned, the receiving chamber 572 is connected to the fuel injection chamber 573 by a connecting passage. Such connecting passage comprises an annular space 584 within the spacer member 534 and nozzle member 533. The connecting passage also includes a radial groove 586 in the lower end of the spacer member 534, which extends between the lower end of the longitudinal bore 574 and the annular space 584.

As in the previous embodiments, a plurality of minute, circumferentially spaced, generally radially extending holes 587 are provided in the lower end of the nozzle member 533, such holes communicating with the fuel injection chamber 573 below the seat 578 in the nozzle member. The outer ends of the holes 587 open into the cylinder with which the injector is associated.

As heretofore mentioned, the ball 576 is mounted in the bore 574 in the spacer member 534. The diameter and length of the bore 574 is such that the maximum volume of the receiving chamber 572 is less than the change in volume of the annular space 584 during the downward or fuel injection stroke of the plunger 546. Thus, the ball 576 will always move to the upper end of its bore 574, regardless of the position of the ball at the start of the downward stroke of the plunger 546. Upward movement of the ball 576 in its bore 574 is limited by a seat 594 formed by the beveled upper end of the bore 574. Since downward movement of the plunger 546 will reduce the volume of the annular space 584 after the ball 576 engages its seat 594, the plunger 546 comprises fluid displacement means for reducing the volume of the annular space 584 and increasing the pressure in the fuel injection chamber 573.

Moreover, since the volume of the receiving chamber will be at a maximum when the ball 576 is engaged with its seat 594 and the plunger 546 is at the end of its upward stroke, the seat 594 comprises a stop for limiting movement of the piston or ball 576 toward the end of the bore 574 opposite from the end that is connected to the portion 548 of the plunger bore and thus the volume of the receiving chamber 572. Consequently, the maximum quantity of fuel that can be injected into the

associated cylinder of the engine by the injector of FIG. 34 is also limited.

In order to provide for a variation of the volume of the receiving chamber 572 and hence variation of the quantity of the fuel injected by the injector of FIG. 34 as a function of the pressure of the fuel in the fuel supply rail, the drain passage is provided. Such drain passage comprises a longitudinal bore 597 in the spacer member 534 which, in the present instance, is smaller in diameter than the bore 574 and extends coaxially therewith. Thus, the lower end of the longitudinal bore 597 is connected to the upper end of the longitudinal bore 574 above the seat 594. The upper end of the bore 597 is connected to the lower end of a bore 598 in the injector body member 532. The bore 598 slants slightly upwardly and outwardly in the body member 532, and the upper end of the bore 598 intersects the inner end of a transverse bore 599 in the body member 532. The outer end of the transverse bore 599 opens into a circumferential groove 602 in the outer surface of the injector body member 532, the groove 602 being adapted to communicate with an associated drain rail in the cylinder head of the engine. Thus, the space in the longitudinal bore 574 above the ball 576 is at all times connected to the drain so that the ball 576 is free to move in the bore 574 in response to the pressure in the annular space 584.

The injector of FIG. 34 further includes pressure relief passage means for relieving the pressure in the receiving chamber 572, and hence in the fuel injection chamber 573 as the plunger 546 is approaching the end of its downward stroke, in order to assure positive termination of injection of fuel into the associated cylinder. Such pressure relief passage means comprises a transverse bore 604 in the spacer member 534, which intersects the portion 548 of the plunger bore and the longitudinal bore 574 below the ball 576 when the latter is engaged with its seat 594.

The outer end of the bore 604 is closed, as by a plug 606, and the inner end, indicated at 607, of the bore 604 communicates with an annular space 608 in the plunger bore portion 548 as the plunger 546 nears the end of its downward stroke. The annular space 608 is provided by a reduced diameter portion 612 on the control portion 547 of the plunger 546 and is in continuous registry with the inner end, indicated at 613, of another transverse bore 614 in the spacer member 534, which intersects the longitudinal bore 597 above the seat 594. The outer end of the bore 614 is closed as by a plug 616. Thus, the pressure in the fuel injection chamber 573 will be relieved when the lower or control edge, indicated at 617, of the reduced diameter portion 612 opens the inner end 607 of the pressure relief bore 604 to vent the receiving chamber 572, and hence the fuel injection chamber 573, to the drain and thus relieve the pressure in these chambers.

As heretofore mentioned, the injector of FIG. 34 involves a novel arrangement for progressively increasing the force of a spring urging the lower end 582 of the valve member 573 toward its seat 578 during injection of fuel into the associated cylinder. Such increased spring force requires an increase in the pressure of the fuel in the fuel injection chamber. This arrangement assures rapid and positive engagement of the lower end 582 of the valve member 583 with its seat 578 and a sharp cutoff of fuel into the associated cylinder when the control edge 617 of the reduced diameter portion

612 of the plunger opens the inner end 607 of the pressure relief bore 604 as the plunger nears the end of its downward stroke.

To provide the foregoing arrangement, the valve member 583 includes an elongated, cylindrical body 622 shiftably mounted in close-fitting relation in an axial bore 623 in the lower part of the control portion 547 of the plunger 546. The valve body 622 is of greater diameter than its lower end, indicated at 624, so that a shoulder or fluid pressure reaction surface 626 is defined at the lower end of the valve body 622.

The valve member 583 is urged outwardly of its bore 623 and toward its seat 586 in the nozzle member 533 by the above mentioned spring which comprises a coil spring 627 disposed around the valve body 622. The upper end of the coil spring 627 bears against the lower end face 575 of the control portion 547 of the plunger 546 and the lower end of the spring 627 engages an abutment in the form of a washer 628 secured to the lower end of the valve body 622. Because of the downward movement of the plunger 546, the force exerted by the spring 627 on the valve member 583 progressively increases and the pressure of the fuel in the fuel injection chamber 573 will therefore continue to increase during the injection phase of the injection cycle until the pressure is relieved by the opening of the inner end 607 of the pressure relief bore 604.

Injection of fuel into the engine cylinder occurs in a manner to be described hereafter in connection with the description of the operation of the injector.

In order to prevent restriction of movement of the valve member 583 in its bore 623 due to the presence of fuel in the space, indicated at 628, between the upper end of the valve body 622 and the inner end of the bore 623, the space 628 is vented to the drain. Such venting is provided by a radial bore 629 in the control portion 547 of the plunger 546, the bore 629 extending outwardly from the space 628 and opening into the space 608 around the reduced diameter portion 612 in the lower part of the control portion 547. Since the space 608 is in continuous registry with the transverse bore 614 of the drain passage, fuel at the drain pressure may flow freely into or out of the space 628. Consequently, the valve body 622 is freely movable in its bore 623.

OPERATION OF THE EMBODIMENT SHOWN IN FIGS. 34-36

At the completion of an injection cycle of the injector shown in FIGS. 34-36, inclusive, and prior to the beginning of another cycle, the parts of the injector are in the positions shown in FIG. 34. Thus, the ball 576 will be at the upper end of the longitudinal bore 574 and will be engaged with the seat 594. In addition, the feed hole 571 is closed at this time by the lower part of the control portion 547 of the plunger 546. Consequently, fuel under pressure from the fuel supply rail is prevented from acting on the ball 576.

As the injection cycle begins, the plunger 546 begins to move upwardly in its bore. During the initial part of such movement and before the lower end face 575 of the plunger 546 opens the feed hole 571, fuel will flow in a reverse direction from the drain rail through the drain passage comprising the circumferential groove 602, transverse bore 599, slanting bore 598, and longitudinal bore 597 into the upper end of the bore 574 above the ball 576. Consequently, the ball 576 will

move downwardly in its bore 574 toward the lower end of the bore due to the transfer of fuel from the receiving chamber 572 into the annular space 584.

When the lower end face 575 of the plunger 546 opens the feed hole 571, fuel from the fuel supply rail will flow into the annular space 584, through the radial groove 586 and into the fuel receiving chamber 572. Consequently, the ball 576 will move upwardly in its bore 574. The extent to which the ball 576 rises in its bore 574 depends upon the quantity of fuel flowing into the annular space 584 and such quantity depends upon the pressure of the fuel in the associated fuel supply rail.

When the plunger 546 reaches the end of its upward stroke, the volume of the receiving chamber 572 will be at a maximum if the pressure of the fuel in the fuel supply rail is great enough to cause the ball 576 to engage its seat 594. However, if the pressure in the supply rail has been less, the ball 576 will be spaced below the seat 594, as shown in FIG. 35, and the volume of the receiving chamber 572 will be less than maximum. The latter condition usually occurs in engines utilizing injectors of the character shown in FIG. 34, when the engine is operating at less than its maximum power output. During the aforementioned upward movement of the plunger 546, the spring 627 expands so that the force exerted by the spring holding the lower end 582 of the valve member 583 on its seat 578 decreases. However, the force of the spring 627 in its fully expanded condition is still great enough to maintain the lower end 582 of the valve member 583 engaged with its seat 578 when the plunger 546 reaches the end of its upward stroke, since the pressure of the fuel acting on the reaction surface 626 is insufficient to overcome the force of the spring 627 throughout the range of fuel supply pressures in the fuel supply rail and fuel supply passage 560.

On downward movement of the plunger 546, the lower end face 575 of the plunger closes the feed hole 571 and thus shuts off the flow of fuel into the space 584. At the same time, the lower end face 575 of the plunger compresses the spring 627 and thereby causes the force exerted by the spring holding the valve member 583 on its seat 578 to increase. It will be understood, that a spring of a different rating could be substituted for the spring 627 to change the closing pressure of the valve member 583. Continued downward movement of the plunger 546 after the plunger has shut off the flow into the space 584 causes fuel to be transferred from the space 584 into the receiving chamber 572. Consequently, the ball 576 will continue to move upwardly in its bore 574 toward its seat 594 until it engages the seat and seals the upper end of the bore 574. When this occurs, the pressure of the fuel in the fuel injection chamber will rapidly rise. Such pressure rise acts on the reaction surface 626 and, when the pressure reaches a predetermined value sufficient to overcome the force of the spring 627, the valve member 583 will lift off of its seat 578, as illustrated in FIG. 36, and open the nozzle holes 587. Consequently, fuel under pressure in the fuel injection chamber 573 will be injected through the nozzle holes 587 into the associated cylinder of the engine. The clearance shown in FIG. 36 between the lower end 582 of the valve member 583 and its seat 578 is exaggerated for clarity of illustration.

Injection of fuel through the nozzle holes 587 continues until the lower or control edge 617 of the reduced diameter portion 612 of the plunger opens the inner

end 607 of the transverse pressure relief bore 604. When this occurs, the pressure in the fuel injection chamber 573 is immediately relieved due to the connection of the fuel injection chamber 573 with the aforementioned drain passage of the injector.

As soon as the pressure in the fuel injection chamber 573 is relieved, the spring 627 shifts the valve member 583 downwardly until the lower end 582 thereof engages its seat 578. Since the lower end face 575 of the plunger 546 increases the compression of the spring 627 while fuel is being injected from the fuel injection chamber 573 through the nozzle holes 587 into the cylinder, the pressure of the fuel in the fuel injection chamber 573 will be substantially higher when the inner end 607 of the pressure relief bore 604 is opened by the control edge 617 of the plunger than when the plunger began its downward or fuel injection stroke. Consequently, when the pressure in the fuel injection chamber 573 is vented to the drain as the plunger 546 is approaching the end of its downward stroke, the lower end 582 of the valve member 583 will be caused to rapidly move into engagement with its seat 578. Therefore, injection of fuel from the fuel injection chamber 573 through the nozzle holes 587 is rapidly or abruptly terminated. In addition, because the force exerted by the spring 627 urging the valve member 583 toward its seat 578 at the time the pressure in the fuel injection chamber is vented to the drain is greater than when injection is initiated, there is less tendency for the lower end 582 of the valve member to remain off of its seat than in a conventional injector. In other words, the increasing force exerted by the spring 627 on the valve member 583 as the plunger 546 moves downwardly in its bore on its fuel injection stroke reduces the possibility of combustion products in the cylinder from being forced through the nozzle holes 587 into the fuel injection chamber 573 and possibly into the fuel supply passage of the injector, which is undesirable. Moreover, any tendency toward secondary injection of fuel into the cylinder after the pressure in the fuel injection chamber is vented to the drain, is also reduced.

Seating of the lower end 582 of the valve member 583 terminates injection of fuel into the cylinder and the injection cycle of the injector shown in FIG. 34.

THE EMBODIMENT SHOWN IN FIGS. 37-42

In FIGS. 37-42, inclusive, another fuel injector embodying the features of the present invention, is illustrated. Many of the parts of the injector shown in these figures are identical with those of the injectors of FIGS. 1 and 20 and therefore have been given the same reference numerals as those of the corresponding parts in FIGS. 1 and 20. The injector of FIG. 37 differs, however, from the previous embodiments in that no separate piston is utilized to determine the volume of a variable volume chamber means in the injector or to shut off the flow of fuel through a drain passage in the injector during the injection phase of the injection cycle of the injector.

The injector shown in FIGS. 37-42, inclusive, comprises an elongated injector body 641 which, in the present instance, is of a multiple-piece construction so that replacement of the parts thereof which are subject to wear or other reason for renewal, is facilitated. However, a unitary or one-piece construction could be utilized, if desired. The injector body 641 includes a generally cylindrical body member 642, a nozzle member

103, and a pair of generally cylindrical spacer members 304 and 105, respectively, located between the body member 642 and nozzle member 103. The nozzle member 103 and spacer members 304 and 105 are arranged and held in end-to-end relation by a tubular retainer 106.

The nozzle member 103 has a fuel injection chamber 143 therein provided by a cavity adjacent the lower end of the nozzle member, and the inner ends of the plurality of minute, circumferentially spaced, generally radially extending holes 157 at the lower end of the nozzle member communicate with the chamber 143 below a valve seat 166 therein. The outer ends of the holes 157 open into the cylinder with which the injector is associated. Communication between the holes 157 and chamber 143 is controlled by a valve member 158 shiftably mounted in an axial bore 160 in the nozzle member 103, the lower end, indicated at 164, of the valve member 158, being tapered and being urged toward the seat 166 in the chamber 143 by a coil spring 172 mounted in a cavity 173 in the spacer member 105. The upper end of the cavity 173 is closed by the spacer member 304.

The spacer members 304 and 105, nozzle member 103 and retainer 106 of the injector shown in FIGS. 37-42, the bores and passages therein, and the other parts of the lower portion of the injector are identical with their like-numbered parts in the injector of FIG. 20. Consequently, no detailed description of these parts of the injector of FIG. 37 will be included.

The injector body member 642 has a central, axial bore 643 therethrough in which a plunger 646 is reciprocably mounted. The plunger 646 comprises a control portion 647 and a sleeve portion 118 secured to the upper end of the control portion 647. The sleeve portion 118, as well as the other parts at the upper end of the injector shown in FIG. 37, are identical in construction and operation with the corresponding parts of the injector shown in FIG. 1, and therefore no further description of these parts will be included.

The injector of FIG. 37 also includes a fuel supply passage, indicated generally at 650, having one end connected to a variable volume chamber means in the injector body 641 and its other end adapted to be connected to a source of fuel under variable pressure. Said other end of the fuel supply passage 650 is provided by a circumferential groove 131 in the outer surface of the injector body member 642, the groove 131 being adapted to register with an associated fuel supply bore or rail in the cylinder head of the engine.

The fuel supply passage 650 also includes a transverse bore 132 which extends inwardly from the groove 131, and a plug 133 having a balancing orifice 134 therethrough is threaded into the outer end of the transverse bore 132. A filtering screen assembly 136 may be mounted in the groove 131 around the plug 133. The balancing orifice 134 and filtering screen assembly 136 of the injector of FIG. 37 perform the same functions as the balancing orifice 134 and filtering screen assembly 136 of the injector of FIG. 1, that is, the balancing orifice 134 restricts and meters the flow of fuel through the fuel supply passage 650 and the filtering screen assembly 136 prevents foreign particles from entering the fuel supply passage.

The inner end of the transverse bore 132 intersects the upper end of a longitudinal bore 652 in the body member 642, and the lower end of the longitudinal

bore 652 is closed as by a plug 653. The longitudinal bore 652 is intersected by another transverse bore 654 in the injector body member 642 below the transverse bore 132. The outer end of the transverse bore 654 is closed as by a plug 657 and the inner end, indicated at 656, opens into the plunger bore 643 and comprises one end of the fuel supply passage 650.

The aforementioned variable volume chamber means of the injector of FIG. 37 is similar to that of the injectors of FIGS. 1 and 20 in that it is also in two parts and comprises the fuel injection chamber 143 and a fuel receiving chamber 662 connected to the fuel injection chamber 143 by a connecting passage 322.

The receiving chamber 662, in the present instance, constitutes a cavity 141 in the upper end face of the spacer member 304 and the portion of the plunger bore 643 below the lower end face, indicated at 665, of the control portion 647 of the plunger 646. Since the plunger 646 determines the volume of the receiving chamber 662, the plunger comprises fluid displacement means for reducing the volume of the receiving chamber 662 and for increasing the pressure therein and in the fuel injection chamber 143. In addition, the lower, full diameter part of the control portion 647 of the plunger 646 comprises preventing means for preventing fuel from flowing from the receiving chamber 662 through the fuel supply passage 650 and into the associated fuel supply rail in the engine cylinder head during the fuel injection phase of the injection cycle.

The aforementioned connecting passage 322 which connects the receiving chamber 662 with the fuel injection chamber 143 is provided by bores and passages identical with those that form the connecting passage 322 of the injector of FIG. 20, and therefore no further description of the connecting passage 322 of the injector of FIG. 37 will be included.

When the plunger 646 starts on an injection cycle, it moves upwardly and tends to create a vacuum in the receiving chamber 662. However, such vacuum is avoided by connecting the receiving chamber to a drain. Such connection is effected by a drain passage in the injector comprising a longitudinal bore 666 (FIG. 38) in the injector body member 642, the lower end of the bore 666 opening in the lower end face, indicated at 667 of the body member 642 so as to communicate with the cavity 141. The upper end of the longitudinal bore 666 intersects a transverse bore 672 in the body member 642, which is positioned above the transverse supply bore 654. The outer end of the transverse bore 672 is closed as by a plug 673, and the inner end thereof, indicated at 674, opens into the plunger bore 643. The transverse bore 672 is cyclically closed before the plunger reaches the end of its upward stroke and cyclically opened before the plunger reaches the end of its downward or fuel injection stroke.

When the inner end 674 of the transverse bore 672 is open, the end 674 communicates with an annular space 676 in the plunger bore 643, the space 676 being provided by a reduced diameter portion 677 on the control portion 647 of the plunger 646. The annular space 676 is in constant registry with the inner end, indicated at 192, of a bore 193 slanting upwardly and outwardly in the injector body member 642 from the plunger bore 643. The outer or upper end of the bore 193 opens into a circumferential groove 194 in the outer surface of the injector body member 642, the groove 194 being adapted to communicate with the

drain rail in the cylinder head of the engine. The drain passage thus prevents the formation of a vacuum in the receiving chamber 662 during the initial upward movement of the plunger 646. The aforementioned drain passage of the injector of FIG. 37 also functions as pressure relief passage means during another portion of the operating cycle of the injector, as will be described more fully hereafter.

Injection of fuel in the engine cylinder occurs in the manner to be described hereafter in connection with the description of the operation of the injector of FIG. 37.

In order to prevent restriction of movement of the valve member 158 due to the presence of fuel in the valve spring cavity 173, the cavity 173 is vented to drain. Such venting is provided by a radial bore 207 in the spacer member 105, which extends from the cavity 173 to an annular groove 208 in the outer periphery of the spacer member 105. The groove 208 opens into an annular clearance 209 between the spacer members 105 and 304 and the retainer 106. The upper end of the clearance 209 communicates with the lower end of a longitudinal bore 678 in the injector body member 642, and the upper end of the bore 678 intersects the slanting drain bore 193 to complete the vent connection to drain.

OPERATION OF THE EMBODIMENT SHOWN IN FIGS. 37-42

At the completion of an injection cycle of the injector shown in FIGS. 37-42, and prior to the beginning of another cycle, the parts of the injector are in the positions shown in FIGS. 37 and 38.

As the injection cycle begins, the plunger 646 begins to move upwardly in its bore. During the initial part of such movement and before the lower or control edge, indicated at 678, of the reduced diameter portion 677 closes the inner end 674 of the transverse bore 672, fuel will flow in a reverse direction from the drain into the receiving chamber 662. The path taken by the flow of fuel from the drain to the receiving chamber 662 includes the circumferential groove 194, slanting bore 193, annular space 676, transverse bore 672 (FIG. 38), longitudinal bore 666 (FIG. 38), and cavity 141. Thus, during this portion of the operating cycle of the injector, fuel is pumped into the receiving chamber 662 due to upward movement of the plunger 646 in its bore and the pressure of the fuel in the receiving chamber 662 is substantially at the pressure of the fuel in the drain.

When the control edge 678 of the reduced diameter portion 677 closes the inner end 674 of the transverse bore 672, the reverse flow of fuel from the drain into the receiving chamber 662 is cut off. Such condition is illustrated in FIG. 39. However, the inner end 656 of the fuel supply passage 650 is not yet opened by the lower end face 665 of the control portion 647 of the plunger. Consequently, a vacuum is formed in the receiving chamber 662 prior to the time that the lower end face 665 of the plunger opens the inner end 656 of the fuel supply passage 650.

When the lower end face 665 of the plunger opens the inner end 656 of the fuel supply passage 650, fuel from the fuel supply rail will flow into the receiving chamber 662. The quantity of fuel flowing into the receiving chamber 662 depends upon the pressure of the fuel in the associated fuel supply rail. Thus, if the pressure in the supply rail is sufficiently high, the receiving

chamber 662 will be completely filled with fuel when the plunger 646 reaches the end of its upward stroke. However, since the volume of the receiving chamber 662 will be at a maximum when the plunger 646 is at the end of its upward stroke and since the stroke of the plunger 646 is constant, the maximum quantity of fuel that can be supplied to the receiving chamber 662 is limited. If the pressure of the fuel in the supply rail is lower, the quantity of fuel flowing into the receiving chamber 662 will be insufficient to completely fill the chamber. The latter condition usually occurs when an engine utilizing injectors of the character shown in FIG. 37, is operating at less than its maximum power output.

On downward movement of the plunger 646, the lower end face 665 of the plunger closes the inner end 656 of the fuel supply bore 654 and thus shuts off the flow of fuel into the receiving chamber 662. Continued downward movement of the plunger 646 after the plunger has shut off the flow into the receiving chamber 662 and has contacted the fuel therein causes the pressure in the receiving chamber 662 to increase rapidly. Such pressure increase is communicated through the connecting passage 322 to the fuel injection chamber 143 and when the pressure reaches a predetermined value sufficient to overcome the force of the spring 172, the valve member 158 will lift off of its seat 166, as illustrated in FIG. 41, and open the nozzle holes 157. Consequently, fuel under pressure in the fuel injection chamber 143 will be injected through the nozzle holes 157 into the associated cylinder of the engine. The clearance shown in FIG. 41 between the lower end 164 of the valve member 158 and its seat 166 is exaggerated for clarity of illustration.

Injection of fuel through the nozzle holes 157 continues until the lower or control edge 678 of the reduced diameter portion 677 of the plunger opens the inner end 674 of the transverse bore 672. When this occurs, the pressure in the receiving chamber 662 and consequently in the fuel injection chamber 143 is immediately relieved due to the connection of these chambers with the aforementioned drain passage in the injector.

As soon as the pressure in the injection chamber 143 is relieved, the spring 172 shifts the valve member 158 downwardly into engagement with its seat 166. Seating of the lower end 164 of the valve member 158 terminates injection of fuel into the cylinder and the injection cycle of the injector shown in FIG. 37. However, due to the location of the inner end 674 of the transverse bore 672, the plunger 646 will continue to move downwardly in its bore 643 for a short distance after the inner end 674 of the bore 672 has been opened. Consequently, fuel in the receiving chamber 662 will be displaced through the drain passage in the injector body member 642 to the drain until the plunger 646 reaches the end of its downward stroke, as shown in FIGS. 37 and 38.

THE EMBODIMENT SHOWN IN FIGS. 43-46

In FIGS. 43-46, inclusive, another fuel injector embodying the features of the present invention, is illustrated. Many of the parts of the injector shown in these figures are identical with those of the injector of FIG. 20 and therefore have been given the same reference numerals of those of the corresponding parts in FIG. 20. The injector of FIG. 43 differs, however, from the previous embodiments in that the high pressure fuel in the variable volume chamber means is vented to the

fuel supply passage, rather than to the drain passage, at the completion of the injection phase of the injection cycle of the injector.

The injector shown in FIGS. 43-46, inclusive, comprises an elongated injector body 681 which, in the present instance, is of a multiple-piece construction so that replacement of the parts thereof which are subject to wear or other reason for renewal, is facilitated. However, a unitary or one-piece construction could be utilized, if desired. The injector body 681 includes a generally cylindrical body member 682, a nozzle member 103, and a pair of generally cylindrical spacer members 304 and 105, respectively, located between the body member 682 and nozzle member 103. The nozzle member 103 and spacer members 304 and 105 are arranged and held in end-to-end relation by a tubular retainer 106.

The nozzle member 103 has a fuel injection chamber 143 therein provided by a cavity adjacent the lower end of the nozzle member, and the inner ends of a plurality of minute, circumferentially spaced, generally radially extending holes 157 at the lower end of the nozzle member communicate with the chamber 143 below a valve seat 166 therein. The outer ends of the holes 157 open into the cylinder with which the injector is associated. Communication between the holes 157 and chamber 143 is controlled by a valve member 158 shiftably mounted in an axial bore 160 in the nozzle member 103, the lower end, indicated at 164, of the valve member 158 being tapered and being urged toward the seat 166 in the chamber 143 by a coil spring 172 mounted in a cavity 173 in the spacer member 105. The upper end of the cavity 173 is closed by the spacer member 304.

The spacer members 304 and 105, the nozzle member 103 and the retainer 106 of the injector shown in FIGS. 43-46, the bores and passages therein, and the other parts in the lower portion of the injector are identical with their like-numbered parts in the injector of FIG. 20. Consequently, no detailed description of these parts of the injector of FIG. 37 will be included.

The injector body member 682 has a central axial bore 683 therethrough in which a plunger 684 is reciprocably mounted. The plunger 684 comprises a control portion 687 and a sleeve portion 118 (FIG. 43) secured to the upper end of the control portion 687. The sleeve portion 118 as well as the other parts at the upper end of the injector shown in FIG. 43 are identical in construction and operation with the corresponding parts of the injector shown in FIG. 1, and therefore no further description of these parts will be included.

The injector of FIG. 43 also includes a fuel supply passage, indicated generally at 690, having one end connected to a variable volume chamber means in the injector body 681 and its other end adapted to be connected to a source of fuel under variable pressure. Said other end of the fuel supply passage 690 is provided by a circumferential groove 131 in the outer surface of the injector body member 682, the groove 131 being adapted to register with an associated fuel supply bore or rail in the cylinder head of the engine. A transverse bore 132 extends inwardly from the groove 131, and a plug 133 having a balancing orifice 134 therethrough is threaded into the outer end of the transverse bore 132. A filtering screen assembly 136 may be mounted in the groove 131 around the plug 133. The balancing orifice 134 and filtering screen assembly 136 of the in-

jector of FIG. 43 perform the same functions as the balancing orifice 134 and filtering screen assembly 136 of the injector of FIG. 20, that is, the balancing orifice 134 restricts and meters the flow of fuel through the fuel supply passage 690 and the filtering screen assembly 136 prevents foreign particles from entering the fuel supply passage.

The inner end of the transverse bore 132 intersects the upper end of a longitudinal bore 692 in the body member 682 and the lower end of the longitudinal bore 692 is counterbored as at 693 to define an annular seat 694 for a check ball 695 mounted in the counterbore 693. The check ball 695 comprises preventing means for preventing fuel from flowing out of a receiving chamber in the injector body 682, to be hereinafter described in detail, and in a reverse direction through the fuel supply passage 690 into the associated fuel supply rail in the engine cylinder head during the fuel injection phase of the injection cycle. The lower end of the counterbore 693 communicates with a shallow, circular cavity or recess 141 in the upper end face of the spacer member 304 and such lower end comprises one end of the fuel supply passage 690. The lower end of the plunger bore 683 opens into the cavity 141.

The aforementioned variable volume chamber means of the injector of FIG. 43 is in two parts and comprises a receiving chamber 142 and the fuel injection chamber 143. The receiving chamber 142 constitutes the cavity 141 and the portion of the plunger bore 683 below a piston in the form of a ball 144 that is loosely fitted in the plunger bore 683 below the lower end face, indicated at 696, of the control portion 687 of the plunger 684. A connecting passage, indicated generally at 322, in the lower end of the injector body 681, connects the receiving chamber 142 with the fuel injection chamber 143. The connecting passage 322 of the injector of FIG. 43 is provided by bores and passages identical with those forming the connecting passage 322 of the injector of FIG. 20, and therefore no further description of the connecting passage 322 of the injector of FIG. 43 will be included.

As heretofore mentioned, a piston in the form of the ball 144 is loosely fitted in the plunger bore 683 between the lower end face 696 of the plunger and the cavity 141 in the upper end face of the spacer member 304. The ball 144 is movable in response to movement of the plunger 684 and determines the volume of the receiving chamber 142. Consequently, the plunger 684 and ball 144 comprise fluid displacement means for reducing the volume of the receiving chamber 142 and for increasing the pressure therein and in the fuel injection chamber 143.

In addition, since the volume of the receiving chamber 142 is determined by the ball 144 and since the volume of the receiving chamber 142 will be at a maximum when the ball 144 is engaged with the end face 696 of the plunger when the latter is at the end of its upward stroke, the end face 696 of the plunger comprises a stop limiting movement of the ball 144 in one direction and the volume of the receiving chamber 142 to a predetermined maximum. Consequently, the maximum quantity of fuel that can be injected into the associated cylinder by the injector of FIG. 43 is also limited.

The injector of FIG. 43 also includes a drain passage which permits variation of the volume of the receiving chamber 142. The drain passage of the injector of FIG. 43 connects the space, indicated at 697, between the

ball 144 and the lower end face 696 of the plunger 684 with the drain rail in the engine cylinder head or other low pressure zone.

The drain passage of the injector of FIG. 43 comprises an axial bore or duct 702 in the lower part of the control portion 687 of the plunger 684, the lower end, indicated at 703, of the duct 702 opening at the end face 696 of the plunger and being located so as to be closed by the ball 144 when the latter engages the end face 696.

The upper end of the duct 702 intersects a cross bore 704 in a reduced diameter portion 706 of the control portion 687 of the plunger, the reduced diameter portion 706 defining an annular space 707 in the plunger bore 683. The annular space 707 is in constant registry with the inner end, indicated at 192, of a bore 193 slanting upwardly and outwardly in the injector body member 682 from the plunger bore 683. The outer or upper end of the bore 193 opens into a circumferential groove 194 in the outer surface of the injector body member 682, the groove 194 being adapted to communicate with the associated drain rail in the cylinder head of the engine. Thus, the space 697 above the ball 144 is connected to the drain so long as the lower end 703 of the duct 702 is not closed by the ball 144. Connection of the space 697 to the drain permits fuel to be freely drawn into the space 697 and thus prevents any substantial vacuum from being created in the space 697 during the upward stroke of the plunger 684, which would tend to cause the ball 144 to remain in contact with or closely follow the lower end face 696 of the plunger 684 on its upward stroke. The ball 144 of the injector of FIG. 43 is thus movable upwardly in the plunger bore 684 substantially only by the pressure of the fuel in the supply passage 690, as in the injector of FIG. 20.

Injection of fuel into the engine cylinder occurs in the manner to be described hereinafter in connection with the description of the operation of the injector.

In order to prevent restriction of movement of the valve member 158 due to the presence of fuel in the valve spring cavity 173, the cavity 173 is vented to drain. Such venting is provided by a radial bore 207 in the spacer member 105, which extends from the cavity 173 to an annular groove 208 in the outer periphery of the spacer member 105. The groove 208 opens into an annular clearance 209 between the spacer members 105 and 304 and the retainer 106. The upper end of the clearance 209 is enlarged as at 210 and communicates with the lower end of a longitudinal bore 712 in the injector body member 682. The upper end of the longitudinal bore 712 intersects the inner end of a radial bore 713 in the body member and the outer end of the radial bore 713 opens into the circumferential groove 194 which communicates with the drain rail in the engine cylinder head, as previously described.

As heretofore mentioned, the injector of FIG. 43 includes novel pressure relief passage means for relieving the pressure in the variable volume chamber means to the fuel supply passage 690 as the plunger 684 is approaching the end of its downward or fuel injection stroke. Such pressure relief passage means, in the present instance, comprises another longitudinal bore 714 in the injector body member 682. The lower end of the longitudinal bore 714 opens at the lower end face, indicated at 715, of the body member 682, into the cavity 141. The upper end of the bore 714 intersects another

transverse bore 716 in the body member 682, which intersects the plunger bore 683 and the longitudinal bore 692 of the fuel supply passage 690 and thus has portions on opposite sides of the plunger bore. The outer end of the transverse bore 716 is closed as by a plug 717. Communication between the portions of the transverse bore 716 on opposite sides of the plunger bore 683 is provided by a circumferential groove 718 in the lower part of the control portion 687 of the plunger 684. The groove 718 is axially located on the lower part of the control portion 687 so as to establish communication between the two portions of the transverse bore 716 on opposite sides of the plunger bore 683 and thus between the longitudinal bores 714 and 692, when the plunger 684 is approaching the end of its downward or fuel injection stroke.

Thus, when the groove 718 establishes communication between the longitudinal bores 714 and 692, pressure in the receiving chamber 142 and consequently in the fuel injection chamber 143 is relieved to the fuel supply passage 690. Relief of pressure in the fuel injection chamber 143 permits the spring 172 to seat the valve member 158. Seating of the valve member 158 terminates injection of fuel into the engine cylinder and the injection cycle of the injector of FIG. 43.

OPERATION OF THE EMBODIMENT SHOWN IN FIGS. 43-46

At the completion of an injection cycle of the injector shown in FIGS. 43-46 and prior to the beginning of another cycle, the parts of the injector are in the position shown in FIG. 43. Thus, fuel under pressure in the receiving chamber 142 maintains the ball piston 144 in the plunger bore 683 engaged with the lower end face 696 of the plunger 684 so that the ball closes the lower end 703 of the duct 702 in the control portion 687 of the plunger 684. The receiving chamber 142 is also connected to the longitudinal bore 692 of the fuel supply passage 690 at this time through the transverse bore 716, groove 718 in the lower part of the control portion 687 of the plunger, and the longitudinal bore 714.

As the injection cycle begins, the plunger 684 begins to move upwardly in its bore. If the pressure of the fuel in the associated fuel supply rail is insufficient to fill the receiving chamber 142 at a rate such as will maintain the ball 144 engaged with the lower end face 696 of the plunger as the plunger moves upwardly, the ball 144 will separate from the lower end face 696 and the space 697 will increase. Such condition is shown in FIG. 44. If the ball 144 separates from the lower end face 696, fuel will flow in a reverse direction from the drain through the drain passage and into the space 697 above the ball 144.

When the plunger 684 reaches the end of its upward stroke, the volume of the receiving chamber 142 will be at a maximum if the pressure of the fuel in the supply rail is great enough to hold the ball 144 in engagement with the lower end face 696 of the plunger 684 and close the lower end 703 of the plunger duct 702. However, if the pressure in the supply rail has been less, the ball 144 will be spaced below the lower end face 696 of the plunger and the volume of the receiving chamber 142 will be less than maximum.

Assuming that the pressure of the fuel in the fuel supply rail has been insufficient to maintain the ball 144 engaged with the lower end face 696 of the control portion 687, as the plunger 684 begins its downward

stroke, fuel in the space 697 will be forced upwardly through the duct 702, outwardly through the cross bore 704 to the annular space 707, and thence through the bore 193 and circumferential groove 194 to the drain rail in the cylinder head of the engine. The volume of the space 697 will decrease until the lower end face 696 of the plunger 684 contacts the ball 144 and the latter closes the lower end 703 of the duct 702. The latter condition is illustrated in FIG. 45.

When the lower end face 696 of the plunger 684 contacts the ball 144 and the ball 144 closes the lower end 703 of the duct 702, continued downward movement of the plunger 684 will cause the pressure in the receiving chamber 142 to rapidly rise. A corresponding pressure rise will also occur in the fuel injection chamber 143 since the fuel injection chamber 143 is connected to the receiving chamber 142 by the connecting passage 322. When the pressure in the fuel injection chamber 143 reaches a predetermined value sufficient to overcome the force of the coil spring 172, the valve member 158 will move upwardly in its bore and the lower end 164 thereof will lift off of its seat 166. Consequently, fuel under high pressure from the fuel injection chamber 143 will be injected through the nozzle holes 157 and into the associated cylinder of the engine. The clearance between the tapered lower end 164 of the valve member 158 and its seat 166 when injection is taking place, is shown exaggerated in FIG. 45 for clarity of illustration.

Injection of fuel through the nozzle holes 157 continues as the plunger 684 continues to move downwardly in its bore until the groove 718 in the lower part of the control portion 687 of the plunger moves into registry with the two portions of the transverse bore 716. When this occurs, the pressure of the fuel in the receiving chamber 142 is immediately reduced to the pressure in the fuel supply passage 690. While the pressure in the fuel supply passage 690 is greater than the pressure in the drain rail, it is substantially less than injection pressure. Consequently, the spring 172 shifts the valve member 158 downwardly in its bore 160 and causes the lower end 164 thereof to engage its seat 166. Seating of the lower end 164 of the valve member 158 terminates injection of fuel into the cylinder and the injection cycle of the injector shown in FIG. 43.

I claim:

1. An injector for injecting fuel into a cylinder of an internal combustion engine, comprising an injector body having a fuel injection chamber provided with an opening adapted to communicate with said cylinder, a valve member in said body and normally closing said opening, said valve member being movable to a position permitting fuel flow from said fuel injection chamber through said opening when the pressure of the fuel in said fuel injection chamber reaches a predetermined value, fluid displacement means movably mounted in said injector body and defining a receiving chamber therein, said injector body also having a connecting passage connecting said receiving chamber with said fuel injection chamber and a supply passage adapted to connect said receiving chamber with a source of fuel under variable pressure for supplying varying quantities of fuel to said receiving chamber, the volume of said receiving chamber being determined by the extent of movement of said fluid displacement means and limited to a predetermined maximum when said fluid displacement means is moved fully in one direction, and said

fluid displacement means being movable in the opposite direction to reduce the volume of said receiving chamber and increase the pressure therein and thereby move said valve member to an open position whereby a quantity of fuel from said fuel injection chamber is injected through said opening into said cylinder, said injector body having a bore therein, said fluid displacement means comprising a piston and a reciprocable plunger in said bore, and said plunger being operable to move said piston in said opposite direction, said receiving chamber being located between said piston and one end of said bore, said plunger having a reduced diameter portion defining a space in said bore and a duct therein having one end communicating with said plunger bore between said plunger and said piston, said one end of said duct being positioned to be closed by said piston during movement of said plunger in said opposite direction, the other end of said duct communicating with said space, and said injector body has a drain bore therein having one end opening into said plunger bore in constant registry with said space and the other end adapted to be connected to a drain, said duct, said space, and said drain bore comprising a drain passage in said injector body permitting fuel to be freely drawn into or expelled from between said plunger and said piston when said one end of said duct is open.

2. An injector for injecting fuel into a cylinder of an internal combustion engine, comprising an injector body having a chamber formed therein and a passage for connecting said chamber with said cylinder, a valve member movably mounted in said passage and normally being in a first position where it closes said opening, said valve member being movable by fuel pressure thereon to a second position where it opens said opening to enable injection of fuel, a plunger and a piston movably mounted in said chamber, said plunger being adapted to be driven in an injection stroke and in a return stroke, said body further including first passage means therein adapted to be connected with a source of fuel under variable pressure and second passage means therein adapted to be connected with a low pressure zone, said first passage means communicating with said chamber on one side of said piston and said second passage means communicating with said chamber on the other side of said piston, said second passage means being open during at least a portion of said return stroke and being closed by said piston during at least a portion of said injection stroke, said plunger exerting pressure on fuel in said chamber when said second passage means is closed during said portion of said injection stroke and thus moving said valve member to said second position, and spill passage means connected to said chamber and located to be opened by movement of said plunger to terminate injection, said plunger and said piston being axially aligned in said chamber, and said second passage means including a hole formed in said plunger.

3. An injector for injecting fuel into a cylinder of an internal combustion engine, comprising an injector body having a chamber formed therein and a passage for connecting said chamber with said cylinder, a valve member movably mounted in said passage and normally being in a first position where it closes said opening, said valve member being movable by fuel pressure thereon to a second position where it opens said opening to enable injection of fuel, a plunger and a piston

movably mounted in said chamber, said plunger being adapted to be driven in an injection stroke and in a return stroke, said body further including first passage means therein adapted to be connected with a source of fuel under variable pressure and second passage means therein adapted to be connected with a low pressure zone, said first passage means communicating with said chamber on one side of said piston and said second passage means communicating with said chamber on the other side of said piston, said second passage means being open during at least a portion of said return stroke and being closed by said piston during at least a portion of said injection stroke, said plunger exerting pressure on fuel in said chamber when said second passage means is closed during said portion of said injection stroke and thus moving said valve member to said second position, and spill passage means connected to said chamber and located to be opened by movement of said plunger to terminate injection, the portion of said chamber containing said valve member being connected to the remainder of said chamber by a connecting passage, said connecting passage opening into said one side.

4. A fuel injector comprising an injector body having a fuel receiving chamber formed therein, a plunger reciprocably mounted in said body and cyclically movable in an injection stroke and in a return stroke, said body having a fuel supply passage therein adapted to be connected to receive fuel from a variable pressure fuel supply and a spill passage therein adapted to be connected to a low pressure zone, said plunger when moving in one portion of its cycle of movement opening said supply passage for flow of fuel from said supply into said chamber and when in another portion of said cycle opening said spill passage for flow of fuel out of said chamber to said zone, said body further having spray holes formed therein and an injection passage connecting said chamber with said spray holes, a fuel pressure actuated valve in said injection passage, said valve being opened by fuel pressure in said chamber and in said injection passage during the time that said supply passage and said spill passage are closed by said plunger during said injection stroke, said pressure in said chamber being caused by movement of said plunger in said injection stroke and the amount of fuel entering said injection chamber being a function of the pressure of the fuel received from said fuel supply down to substantially zero fuel supply pressure, and further including a member movably mounted in said body and having one side thereof forming a wall of said receiving chamber, said body further having passage means therein adapted to connect a low pressure zone to the side of said member which is opposite said one side, whereby said member is movable to vary the size of said chamber as fuel flows into said chamber from said supply and said passage to said zone prevents suction from occurring while said plunger is moving in said return stroke, the flow of fuel from said supply passage and into said chamber being controlled only by the movement of said plunger, whereby the quantity of fuel flowing into said chamber is determined by the pressure of the fuel from said supply and may be varied down to substantially zero quantity.

5. A fuel injector comprising an injector body having a fuel receiving chamber formed therein, a plunger reciprocably mounted in said body and cyclically movable in an injection stroke and a return stroke, said

body having a fuel supply passage therein adapted to be connected to receive fuel from a variable pressure fuel supply and a spill passage therein adapted to be connected to a low pressure zone, said plunger when moving in one portion of its cycle of movement opening said supply passage for flow of fuel from said supply into said chamber and when in another portion of said cycle opening said spill passage for flow of fuel out of said chamber to said zone, said body further having spray holes formed therein and an injection passage connecting said chamber with said spray holes, a fuel pressure actuated valve in said injection passage, said valve being opened by fuel pressure in said chamber and in said injection passage during the time that said supply passage and said spill passage are closed by said plunger during said injection stroke, said pressure in said chamber being caused by movement of said plunger in said injection stroke, and a member movably mounted in said body and having one side thereof forming a wall of said receiving chamber, said body further having passage means therein adapted to connect a low pressure zone to the side of said member which is opposite said one side, whereby said member is movable to vary the size of said chamber as fuel flows into said chamber from said supply and said passage to said sump prevents suction from occurring while said plunger is moving in said return stroke, the flow of fuel from said supply passage and into said chamber being controlled only by the movement of said plunger, whereby the quantity of fuel flowing into said chamber is determined by the pressure of the fuel from said supply and may be varied down to substantially zero quantity.

6. A fuel injector as in claim 5, and further including fuel flow restricting orifice means mounted in said supply passage.

7. An engine injector for operation in a fuel system including means for supplying fuel to said injector and for controlling the fuel pressure in order to control the quantity of fuel injected by the injector in each cycle of operation, said injector comprising an injector body having chamber means formed in said body and connected to receive fuel through a normally open passageway from said pressure controlling means, the quantity of the fuel flowing into said chamber means being a function of the pressure of the fuel, spray holes formed in said body for connecting said chamber means with a combustion chamber of the engine, a normally closed valve positioned to control the flow of fuel out of said chamber means through said holes, said valve being openable to enable fuel flow only when the fuel pressure in said chamber means is above a predetermined value, fluid displacement means mounted in said body and reciprocably movable in an injection stroke and in a retraction stroke, said displacement means during said injection stroke trapping fuel in said chamber means and exerting pressure on said trapped fuel to above said predetermined value and thereby opening said valve, spill port means connected to said chamber means and located to be opened by movement of said displacement means at the end of said injection stroke, said opening of said spill port means venting a portion of said trapped fuel from said chamber.

ber means and resulting in prompt closure of said valve, and said body further having passage means therein adapted to be connected to a low pressure fuel zone, said passage means being open during at least a portion of said retraction stroke to permit low pressure fuel to flow from said zone into said chamber means during said retraction stroke.

8. An injector as in claim 7, and further including means in said normally open passageway forming a balance orifice.

9. An injector as in claim 7, wherein said spill port means is connected to vent trapped fuel to said low pressure fuel zone.

10. An injector as in claim 7, wherein said spill port means is connected to vent trapped fuel to said normally open passageway.

11. An injector as in claim 7, wherein said normally closed valve means includes a valve seat, a valve member, and a spring urging said valve member toward said valve seat, one end of said valve member being exposed to said trapped fuel pressure in said chamber means, and the other end of said valve member being exposed to said low pressure fuel zone.

12. An injector as in claim 11, wherein said plunger engages said spring and varies the force exerted by said spring with movement of said plunger.

13. An injector as in claim 7, wherein said displacement means comprises a plunger and a piston, said piston being movable in said chamber means.

14. An injector as in claim 13, wherein said plunger and said piston are movable along a single axis.

15. An injector as in claim 13, wherein said plunger is movable along a first axis and said piston is movable along a second axis, said first and second axes being laterally displaced in said injector body.

16. An injector as in claim 13, wherein the pressure of said trapped fuel in said chamber means urges said piston in a first direction, and further including a metering spring connected to said piston and urging said piston in the opposite direction against said pressure of said trapped fuel.

17. An injector as in claim 16, wherein said metering spring is a linear spring.

18. An injector as in claim 13, wherein said piston is movable to close said passage means during said injection stroke, said piston being moved by fuel pressure caused by movement of said plunger.

19. An injector as in claim 18, wherein a portion of said passage means is formed in said plunger, and said plunger and said piston engage to close said portion of said passage means during said injection stroke.

20. An injector as in claim 13, wherein said normally open passageway, said spill port and said spray holes are all connected to said chamber means on one side of said piston, and said passage means is connected to said chamber means on the other side of said piston.

21. An injector as in claim 20, wherein said one side of said piston comprises its side which is adjacent said plunger.

22. An injector as in claim 20, wherein said one side of said piston comprises its side which is away from said plunger.

* * * * *
